UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

TELEPHONE-EXCHANGE SYSTEM.

1,109,650.

Specification of Letters Patent.

Patented Sept. 1, 1914.

Application filed June 16, 1906, Serial No. 322,079. Renewed March 27, 1907. Serial No. 364,754.

To all whom it may concern:

Be it known that I, TALBOT G. MARTIN, a citizen of the United States of America, and resident of Chicago, Cook county, Illinois, 5 have invented a certain new and useful Improvement in Telephone-Exchange Systems, of which the following is a specification.

My invention relates to telephone systems in general, but more particularly to automatic or semi-automatic telephone exchange systems, and especially to systems in which the current for both talking and switching purposes is supplied to the telephone lines from a common battery or other centralized 10 source of supply located at the exchange or central station.

In certain respects my present invention is in the nature of an improvement on the system and apparatus disclosed in my prior application Serial No. 319,255 filed by me in the United States Patent Office on the 29th day of May, 1906.

Generally stated the object of my present invention is the provision of an improved and highly efficient telephone system involving improved apparatus for trunking in opposite directions over one and the same trunk-line.

Special objects of my invention are the provision of two-way trunks in combination with a common battery or other suitable centralized source of talking and switching current; the provision of automatic means for automatically trunking in one direction over a two-way trunk-line, in combination with separate and distinct automatic means for trunking in the opposite direction over said line; the provision of two-way trunks each provided at its opposite ends with repeaters and selectors, the selectors and repeaters being distinct and separate from each other, the repeater at one end being adapted to coöperate with the selector at the other end for trunking over the line in one direction, and the other repeater and selector being adapted to coöperate with each other in automatically trunking over the line in the opposite direction; and the provision of certain details and features of improvement, 30 together with certain novel circuit arrangements and combinations tending to increase the general efficiency of a telephone exchange system of this particular character.

To the foregoing and other useful ends,

my invention consists in matters hereinafter set forth and claimed.

Figures 1, 2 and 3 taken together represent the circuits and switches involved when a subscriber at one exchange (Fig. 1) calls a subscriber at a second exchange (Figs. 2 and 3) over a two-way trunk embodying the principles of my invention. In Fig. 1 the calling substation X is shown connected to a first-selector A located at the central exchange #1, said first-selector being allotted to said line. The said switch has normal connection with the central battery B of the central office #1. To the right of the selector A an improved repeater C has an important part in the operation of the system. 70 To the right of said repeater is shown one of the improved step-by-step selector-switches D which is of the same general class to which the selector A belongs. The said repeater C and the improved selector D are allotted to one of the trunk-lines that connect central #1 with central #2. The said switch D, from the position that it holds in the system, is known as a second-selector. In Fig. 2 C¹ represents the repeater at exchange #2 allotted to the same trunk-line and the associated selector D¹ is shown to the right of said repeater C¹. The repeaters C and C¹ and the second-selectors D and D¹ are similar. In Fig. 3 the connector-switch E is allotted to the central #2, and to the right of said connector is shown the first-selector A¹ allotted to the called subscriber's line. The said selector-switch A¹ is similar to the first-selector A. In said Fig. 3 the 90 called substation #2220 is also shown, and is, of course, connected to its allotted first-selector A¹. Fig. 4 is a diagrammatic perspective view of the first-selector A. Figs. 5 and 6 are similar views of the improved selector D¹ and connector E, respectively. Fig. 7 is a simplified diagrammatic drawing showing the circuits through which the talking currents and the voice currents are conducted when two subscribers are connected. 100 At the substations the secondary windings and their receivers in series with said windings are not shown.

The subscriber at substation X, in establishing connection with the subscriber 105 #2220, operates his dial (which is not shown) four distinct times, once for each digit of the number called. Upon operat-

ing his dial for the first digit the first-selector A raises the line and private wipers of the switch-shaft to the second level of their banks and rotates them into connection with an idle trunk-line leading, for example, to the repeater C. The wipers might have stopped in connection with some other trunk-line leading to some other repeater similar to the repeater C; but as soon as the connection is established with the repeater C a guarding potential is established by the first-selector A at all bank multiples by which the repeater C may be seized. The same guarding potential causes the vertical switching relay *a* of the repeater C to be energized and to perform, among others, three operations. First, the vertical trunk-conductor *b* that connects the two exchanges is disconnected from the vertical line relay *c* of the second-selector D. Second, the said vertical trunk-conductor *b* between the two exchanges is connected to ground by the said relay *a*. Third, at the same time the rotary switching relay *d* is also pulled up. The said rotary switching relay *d* at once cuts off the said ground connection to the vertical trunk-conductor *b*. Since the energizing of the rotary switching relay *d* follows close upon the energization of the vertical switching relay *a* the ground impulse given to the aforesaid vertical trunk-conductor *b* is quite short or momentary in character. Not only does the rotary switching relay *d* cut off the ground from the said vertical trunk-conductor *b*, but at the same time it disconnects the rotary trunk-conductor *e* of the trunk-line connecting the two exchanges from the rotary line relay *f* of the second-selector *d*. The said ground impulse delivered to the vertical trunk-conductor *b* passes through the repeater C¹ of the second exchange without operating said repeater, and energizes the vertical line relay *g* of the second-selector D¹. Said vertical line relay *g* then causes the vertical magnet *h* to attract its armature *i*, which latter draws the release-link *j* from the double-dog *k*, whereby the latter causes the spring *l* to engage the ground contact *m*, thereby placing a guarding potential at all multiple terminals *n* of the repeater C¹ to prevent any selectors of the second exchange from seizing said repeater C¹ in the same manner that the first-selector A seized the repeater C. It will be noticed by referring to Fig. 5 that while the double-dog *k* is retained in normal position by the release-link *j* the pawl *o* is prevented from engaging the circular teeth *p*; but as soon as the double-dog *k* is released, as described, then the said pawl *o* is adapted to raise the shaft of the switch D¹. The subscriber having thus seized and appropriated to his use the trunk-line leading from the repeater C then operates his dial for the second digit. The

second-selector D¹ is then operated to raise the switch-shaft wipers to the second level of the switch-bank and to rotate the said wipers into engagement with an idle trunk leading to the connector E. As soon as the 70 said trunk-line is seized it is, of course, protected by a guarding potential to prevent any other switch from connecting with the said connector E, for the time being. The subscriber then operates his dial for the 75 third digit, whereby the shaft of the connector is raised to the second level. Then again the subscriber operates his dial for the last digit and rotates the said connector-shaft so that the line wipers are carried into 80 engagement with the contacts or terminals of the line-conductors of the desired subscriber.

In detail the apparatus is constructed as follows: The subscriber's station may be of 85 any suitable, known or approved type. Said substation is provided with a well-known impulse-wheel 2 which has the usual vertical impulse teeth 3 that are adapted to operate the vertical impulse spring 4 in such 90 a manner that the said spring may be pressed intermittently against the ground post 5 for the purpose of sending ground impulses to the vertical line-conductor of the subscriber's line. Furthermore, the said 95 impulse-wheel carries a rotary impulse finger 6 which, after the vertical impulses are sent, acts upon the rotary impulse spring 7 so that one ground impulse is sent to the rotary side of the subscriber's line. The 100 substation is, of course, provided with a suitable switch-hook 8. Said switch-hook has a number of cam-arms 9, 10 and 11 for controlling certain operations and circuits of the substation. The cam-arm 11 controls 105 the so-called locking arm 12 in such a manner that when the switch-hook rises, and before the dial (which is not shown) is rotated, the insulating tip 13 upon the end of the locking cam 12 that normally rests in 110 a position shown at substation #2220 is driven to the inner edge of the angled section provided at the end of the so-called ground spring 14, whereby when the dial is pulled down by the calling subscriber 115 15 upon the end of the locking dog 16 is able to pass beneath the said locking cam to raise the said cam a little, causing the said insulating tip 13 to fall behind the said angled section of the ground spring 14, 120 permitting said spring, therefore, to make electric contact with a coöperating ground spring 17. The engagement of the said ground springs 14 and 17, upon the operation described, places the ground post 5 in 125 connection with the substation ground, whereby when the subscriber releases the dial, after pulling it down as described, the vertical impulse teeth 3 will first act upon the vertical impulse spring 4; and after that 130

the rotary impulse tooth 6 acts upon the rotary impulse spring 7, as previously described. The subscriber is, of course, provided with a transmitter 18 and induction-coil 19, the primary winding 20 of which is connected normally, when the switch-hook is raised, in series with the transmitter 18 and across the subscriber's line; and the secondary winding 21 is connected into a local closed circuit in series with the receiver 22. Furthermore, the substation is provided with a finger 23 that is normally bridged across the subscriber's line, when the switch-hook is down, in series with a condenser 24. When the switch-hook is down, as stated, the cam-arm 10 maintains the switch springs 25 and 26 in contact, whereby said ringer is maintained across the line; but the spring 25 being depressed, the other two springs 27 and 28 are then retained normally separated, which springs, when the switch-hook rises, are normally closed while the springs 25 and 26 are apart. It will be noticed that the said springs 27 and 28 control the connection between the two conductors of the subscriber's line through the aforesaid transmitter 18 and through the primary winding 20 of the induction-coil 19. Even after the switch-hook is raised, since the finger 29 of the cam-dog 16 controls the engagement of the springs 27 and 28, and since the said cam-dog rotates in unison with the dial as long as the said dial is out of normal position, the springs 27 and 28 and, therefore, the subscriber's line conductors are kept separated for the time. The signaling device whereby a subscriber may signal a called subscriber, after he has established connection, comprises a push-button 30 and spring 31, which latter normally engages a contact point 32; but when the push-button 30 is pressed the spring 31 braces the contact 32 and passes into engagement with the contact point 33, which latter is, during the time for signaling, connected with ground. The means whereby the subscriber may release the central office switching apparatus, after said apparatus is once disturbed or run in use, comprises three release-springs 34, 35 and 36, controlled by the cam-arm 9, that when the switch-hook descends the said springs are pressed into contact, whereby both sides of the subscriber's line are grounded simultaneously.

The first-selector A is of a well-known type. Said selector is provided with a switch-shaft 37 for carrying the line wipers 38 and 39 and the private wiper 40. Said shaft is operated vertically by the vertical magnet 41 for raising the said wipers to any desired row or level of the line and private banks 42 and 43, respectively. Being raised the shaft is rotated by the rotary magnet 44. The release-magnet 45 is employed for releasing the switch after it has been operated.

The vertical and rotary line relays 46 and 47, the bridge-cut-off-relay 48, back-release-relay 49 and private magnet 50 are auxiliaries for controlling said vertical, rotary and release magnets. The switch-shaft, in addition to the details already described, has the usual cam 51, the longitudinal teeth 52 for rotating the shaft, and the circular teeth 53 for raising it. Associated with said circular teeth is the channel 54 normally occupied by the shaft rest 55. The switch-shaft is maintained in normal rotary position by the normal post 56 and the normal post arm 57 against which post the said arm 57 is retained by the spring 58. The connector E is also of a well-known type. In construction it is very similar to the first-selector, although the circuits are quite dissimilar. Said connector is also provided with a switch-shaft 59 and wipers 60, 61 and 62 to which are allotted the line and private banks 63 and 64, respectively. There is also a shaft-cam 65, the longitudinal teeth 66, circular teeth 67, shaft rest 68, normal post 69, normal post arm 70 and the coil-spring 71. Furthermore, there is the vertical magnet 72, the rotary magnet 73, and the release-magnet 74; and in addition to the auxiliary vertical and rotary line relays 75 and 76, the differential relay 77, the back-bridge-relay 78, and the private magnet 79. The connector has a special relay known as the ringer-relay 80 for connecting the ringer-generator 81 across the called subscriber's line when a connection is established.

The repeater C comprises a number of relays and coils that may be assembled about any suitable base or frame to form a unit, if desired. It comprises the vertical switching relay *a*, the rotary switching relay *d*, the differential relay 82, a pole-changing-relay 83, a vertical line relay 84 and a rotary line relay 85. The said vertical and rotary line relays are connected in series with the windings 86 and 87 of the differential relay 82. The repeater C is provided with a couple of repeating-coils 88 and 89, the former having the windings 90 and 91 and the latter the windings 92 and 93. The windings 90 and 92 are separated by the condenser 94, and the windings 91 and 93 by the condenser 95. The repeater has in addition a dead resistance coil 96 which is included in a trunk release circuit to be described. The line relays 84 and 85 control between them the springs 97, 98, 99, 100 and 101. The differential relay 82 controls the springs 102, 103, 104 and 105, while the pole-changing-relay 83 has under its control the springs 106, 107, 108, 109, 110 and 111. The vertical switching relay *a* has allotted to it the springs 112, 113, 114, 115, 116 and 117 and the rotary switching relay *d* has allotted to it the springs 118, 119, 120, 121 and 122.

The method of operation of the switch D^1 is the same as that of the selector A and the circuits are practically the same. The only difference consists in the omission of a 5 bridge-cut-off-relay, so that the vertical and rotary line relays g and 123 are connected directly to the central battery, and not through a number of springs. In the 10 first-selector A (Fig. 4) it will be noticed that the bridge-cut-off-relay 48 controls the springs 124, 125 and 126 and through these 15 springs the connection between the vertical and rotary line relays 46 and 47 to the main battery B is established. There is no necessity for such a relay in the second-selector 20 D^1 and, therefore, it is omitted. Another point of distinction is that the pawl o of the second-selector D^1 is normally engaged by a pin 127 attached to the double-dog k . 25 The arrangement is such that when the double-dog k is in normal position the said pin 127 engages the stock 128 of the pawl o , preventing said pawl from engaging the circular teeth p , as stated, when the vertical 30 armature i is attracted while the link j is in engagement with the double-dog k . In the first-selector A the vertical pawl 129 has no such adjustment, so that at the very first impulse of the vertical armature 130 the shaft 35 37 is raised. In the second selector D^1 , when the double-dog is released from the controlling link j , the pin 127 passes sufficiently rearward to leave the said pawl o unobstructed. Furthermore, the group of springs 40 131, 132 and 133 is not found in the second-selector D^1 , but instead similar springs are placed under the control of the double-dog k . Said springs l , m and 134 are so adjusted that the spring l normally engages the 45 spring 134, but whenever the double-dog is released from the link j the springs l and m engage instead; otherwise there is no difference between the said first and second 50 selectors.

55 As in the first-selector the release-armature retracting-spring 135 retains the vertical and rotary dogs 136 and 137 away from the shaft 138 while the double-dog is latched by the release link j , but when the 60 double-dog is released by the vertical arm 139 the double-dog retracting-spring 140 draws the said dogs toward the shaft in such a manner that the dog 136 by engaging the circular teeth p prevents the shaft from falling when raised by the vertical pawl o upon the end of the vertical arm 139 and when the vertical magnet h is energized. When the 65 rotary magnet 141 is energized the rotary armature 142 is attracted, and among other 70 things that follow the shaft 138 is rotated by the rotary pawl 143 of the rotary arm 144. When the said rotary pawl engages the longitudinal teeth 145, the rotary armature finger 146 at the same time depresses 75 the private armature 147; also the inter-

rupter finger 148 separates the interrupter springs 149 and 150 to destroy the energizing circuit through the rotary magnet 141, as will be described. The interrupter here represented by the interrupter finger 148 and 70 the springs 149 and 150 is of a well-known type. When the shaft is rotated the rotary dog 137 engages the longitudinal teeth 145 and locks the shaft against any possible backward rotation by the tension of the 75 shaft coil-spring 151.

It should be understood that each of the exchanges herein referred to has its own battery. The exchange #1 is provided with a 80 battery B, as stated, which preferably has its positive pole or terminal grounded at G, and the exchange #2 has a battery B^1 similarly grounded at G^1 .

More specifically considered the switching operations are as follows: When the subscriber at the substation X wishes to call the subscriber #2220 he removes his receiver 22 from the switch-hook 8 and thereby causes the cam-arm 11 to fully raise the locking cam 12, as already described. The calling subscriber then begins by turning his dial for the first digit 2, thereby grounding the vertical line conductor 152 twice, and then the rotary line conductor 153 once upon the return motion of the dial. Grounding the 90 vertical line conductor 152 twice energizes the vertical line relay 46 of the first-selector A. As the dial is pulled, and as previously described, the insulating tip 13 clears the ground spring 14 and places the ground post 100 5 in connection with the substation ground G^2 , so that when the vertical impulse spring 4 is pressed against the ground spring 5 the circuit through the said vertical line relay 46 then extends from ground G^2 through the 105 ground springs 14 and 17 to the ground post 5, thence to the vertical impulse spring 4, vertical line conductor 152 and side switch wiper 154, contact-point 155, conductor 156, vertical line relay 46, conductor 157, bridge-cut-off-relay springs 125 and 126, conductors 158 and 159 to the battery lead 160, thence through battery B to ground G. When the vertical line relay 46 becomes magnetized it 110 attracts its armature 161 and forces the spring 162 onto the ground spring 163, thereby closing a circuit through the vertical magnet 41 in series with the battery B. Energizing current will flow through the vertical magnet 41 from ground G^3 and through 115 the springs 163 and 162, conductor 164, private springs 165 and 166 to the vertical magnet 41, thence to the battery lead 160 and through battery B to ground G. The vertical magnet is energized twice, since the vertical line relay 46 is energized twice, and thereby attracts its armature 130 twice. The 120 vertical magnet 41, upon attracting the vertical armature 130 twice, and through the medium of the vertical arm 167, causes the 125 130

vertical pawl 129 to engage the circular teeth 53 and raise the shaft 37 one step at a time. At the first step of the vertical arm 167 the release-link 168 is disengaged by the L-shaped piece 169 from the double-dog lug 170 of the double-dog 171, so that the vertical dog 172 engages the circular teeth 53 to catch and hold the shaft in the first raised position. The shaft having been raised two steps the line and private wipers are thereby raised to the second level and brought opposite the first contact of the second level of their respective banks in readiness to be rotated into engagement with the contacts of said banks. When the rotary line conductor 153 is grounded the rotary line relay 47 of the first-selector is energized and the said relay then causes the private magnet 50 to be magnetized for operating the side switch H. The energizing circuit for the rotary line relay 47 may be traced from the substation ground G² to the ground post 5, thence through the rotary impulse spring 7 to the rotary line conductor 153, side switch wiper 173, contact-point 174, conductor 175, rotary line relay 47, bridge-cut off-relay springs 124, 125 and 126 to the battery lead 160 and through battery B to ground G. The rotary line relay 47 then attracts its armature 176 and thereby presses the spring 177 onto the ground spring 163. The electric current will then flow from ground G² through the springs 163 and 177, conductors 178 and 179 to the private magnet 50, thence to the battery lead 160 and through battery B to ground G.

Assuming that the first nine contacts of the second level of the private bank 43 are busy and, therefore, that the first nine trunks of the second level of the line bank 42 are in use, when the private magnet 50 by operating its armature 180 causes the side switch H to pass to second position an energizing circuit is then established through the rotary magnet 44 to rotate the shaft one step. At the first step the private wiper 40 meets a guarding potential at the first contact of the second level of the private bank 43, so that the private magnet 50 is again energized for locking the side switch in second position until the rotary magnet 44 has carried the wipers past all busy trunk-lines. The private magnet upon becoming energized, as described, attracts the private armature 180, whereby the escapement-tooth 181 clears the escapement-finger 182, and the retracting-spring 183 advances the escapement-finger 182 against the upper rearmost escapement-tooth 184. When the private armature returns to normal position the escapement-finger 182 clears in turn the tooth 184 and the lug 185 at the base of the finger 182 strikes the cam 51 and retains the said escapement-finger 182 between the teeth 181 and 185. Of course it will be understood that the retracting-spring 183 provides the force that continually advances the side switch from one position to another during the call. When the side switch passes to second position the side switch wiper 187 engages the grounded contact 188, whereby an energizing circuit for the rotary magnet 44 is established. The current in this circuit passes from ground G² to the contact-point 188, thence to the side switch wiper 187, conductor 189, to one of the coils 190 of the rotary magnet 44, thence through the spring 191 and 192 and through the other coil 193 of the rotary magnet to the battery lead 160 and through battery B to ground G. The rotary magnet upon attracting the rotary armature 194 rotates the shaft 37 one step so that the private wiper 40 engages the first contact of the second level of the private bank 43. The said contact being grounded the private magnet 50 is energized again as follows: from the ground terminal G of battery B and through an occupying switch and bank multiplying conductors to the first contact of the second level of the private bank 43, thence to the private wiper 40, conductor 195, back-release relay 49, conductor 196 to the side switch wiper 197, thence to the contact-point 198, conductors 199 and 179 to the private magnet 50, thence to the battery lead 160 and through battery B to ground G. The private magnet then attracts its armature 180 and locks the escapement-finger 182 behind the tooth 200. This, of course, occurs before the cam 51 leaves the lug 185. The side switch being thus locked in second position the rotary magnet 44 is energized intermittently as long as the private wiper 40 finds busy contact-points along the second level of the private bank 43. As a result the rotary armature 194 is attracted and the shaft is rotated step-by-step until the wipers are carried into engagement with the tenth trunk-line of the second level, which, as has been stated, is the only trunk-line on said level that is idle. At the instant that the private wiper 40 leaves the last busy contact the energizing circuit through the private magnet 50 is destroyed and the side switch H passes to third position and the escapement-finger 182 falls against the side switch stop 201. The side switch wipers 154 and 173 then engage the contact-points 202 and 203 and the side switch wiper 197 engages the contact-point 204. The side switch wipers 154 and 173 thus extend the subscriber's line conductors 152 and 153 by way of the conductors 205 and 206 and line wipers 38 and 39, respectively, to the trunk-conductors 207 and 208, as shown in Fig. 1.

The engagement between the side switch wiper 197 and contact-point 204, as described, places a guarding potential at the tenth contact of the second level of the

private bank 43. The connection between said contact and ground is as follows: from ground G^5 to the contact-point 204, thence to the side switch wiper 197 and through 5 the back-release-relay 49 to the private wiper 40 and to the said contact. The seized trunk-conductors 207 and 208 are thus protected from seizure by other first-selectors which have multiplied contacts at the said 10 seized trunk. At the instant that the said guarding potential is established at the said tenth contact of the second level the vertical switching relay a of the repeater C is energized. Said relay receives current from 15 the first-selector A from the ground G^5 to the private wiper 40, thence to the trunk-release-conductor 209, conductor 210, second-selector springs 1¹ and 134^a, conductor 211 to the vertical switching relay a , thence 20 to the battery lead 160 and through battery B to ground G. It will be observed that this circuit includes the relay 49 of the first-selector A, but the relay a is of such high resistance as compared with the relay 25 49 that sufficient current does not flow to operate the relay 49. The switching relay a alone operates. The said relay upon becoming energized presses the springs 112, 113 and 114 into contact, and as a result two operations are simultaneously accomplished, namely: A ground connection is established 30 to the vertical trunk-conductor b and an energizing current is sent through the rotary switching relay d . The circuit by which the 35 said ground connection is established may be traced from ground G^5 to the springs 112, 113 and 114, thence through the springs 119 and 118 of the rotary switching relay d and to the vertical trunk-conductor b . The 40 energizing circuit through the rotary switching relay d extends from the same ground G^5 through the springs 114 and 113 and to the said relay d , thence to the battery lead 160 and through battery B to ground G. 45 As soon as the said relay becomes energized it attracts its armature and thereby separates the springs 118 and 119 so that the ground circuit to the vertical trunk-conductor b , described, is at once interrupted. The 50 said momentary and preliminary ground impulse to the vertical trunk conductor b causes the vertical magnet h of the selector-switch D¹ at the second exchange to be energized sufficiently to disengage its release-link j from the double-dog lug 212, but not 55 sufficiently to cause the shaft 188 of said switch to be raised. The said release-link being disengaged, as described, the armature 213 of the release-magnet 214 is then withdrawn 60 farther from the core of the release-magnet by the retracting-spring 135, and as a result the spring l engages the ground spring m and establishes a guarding potential over the trunk-release-conductor 215 to 65 all first-selector private bank contacts n that are multiplied to said trunk-release-conductor. Therefore, the seized trunk is not only protected from seizure at the first central office, but at the second central office as well. Not only is a short electric impulse sent over 70 the vertical trunk-conductor b by the energization of said vertical and rotary switching relays a and d , as described, but certain circuits are changed, as follows: For instance, when the vertical switching relay a 75 is energized the vertical line relay c that is normally connected to the vertical trunk-conductor b is disconnected from said trunk-conductor and the said trunk-conductor is connected instead with the winding 90 of 80 the repeating-coil 88. The normal connection with the said vertical trunk-conductor b is as follows: from said relay c over the conductor 216 to the contact-point 217, side switch wiper 218, conductor 219, through 85 the vertical switching relay springs 115 and 116 to the said vertical trunk-conductor b . The connection between the vertical trunk-conductor b and the winding 90 of the repeating-coil is established, as shown 90 in Fig. 1, through the springs 116 and 117 of the vertical switching relay a . Furthermore, when the rotary switching relay d is energized the rotary line relay f of the selector D, in a similar manner, is changed 95 from normal connection with the rotary trunk-conductor e , and the said trunk-conductor is connected instead with the winding 92 of the repeating-coil 89. The normal connection between the rotary line relay f 100 and the said outgoing rotary trunk-conductor e may be traced from the said relay f to the conductor 220, contact-point 221, side switch wiper 222, conductor 223 and springs 122 and 121 of the rotary switching 105 relay d to the said rotary trunk-conductor e . The temporary circuit between the said rotary trunk-conductor e and the winding 92 of the repeating-coil 89 is established through the springs 121 and 120 of the 110 rotary switching relay d . Therefore, when the two switching relays a and d are energized the vertical and rotary line relays c and f of the selector D are cut off from the 115 trunk-line-conductors b and e , and instead the said conductors are connected through the windings 90 and 92 of the repeating-coils 88 and 89, respectively, and through the condenser 94. Therefore, by the first 120 operation of the dial the calling subscriber at the substation X establishes connection with the repeater C and sets up a guarding potential to prevent any one else from establishing connection with said repeater, which guarding potential also energizes, 125 first, the vertical switching relay a and, second, the rotary switching relay d , thereby sending a ground impulse over the vertical trunk-conductor b to operate the vertical magnet h of the second selector D¹ at the 126 13

distant exchange; establishing a guarding potential at the other end of the trunk-line that leads from the selector D. The pulling up of the relays *a* and *d* disconnects the line 5 relays *c* and *f* of the selector D from the trunk-line and closes a circuit between the conductors of said line, as described. The calling subscriber then proceeds and operates his dial for the second digit 2, ground- 10 ing, as before, the vertical line conductor 152 twice and the rotary line-conductor 153 once. Each time that the vertical line-conductor 152 is grounded the vertical line relay 84 of the repeater C and the differential relay 82 are energized. The flow of current 15 in the energizing circuit passes from ground G² to the vertical trunk-conductor 152, when the vertical impulse spring 1 is operated, and then passes to the side switch 20 wiper 154 of the first selector A, contact-point 202, conductor 205, vertical line wiper 38, vertical trunk-conductor 206, vertical line relay 84, winding 86 of the differential relay 82 to the battery lead 160 and through 25 battery B to ground G. Since the winding 86 is in series with the line relay 84 the differential relay energizes and separates the springs 102 and 103 to prevent the pole-changing-relay 83 from being energized 30 over circuits that will be presently referred to. When the vertical line relay 84 is energized the springs 100 and 99 are pressed into contact for repeating the ground impulses received by the vertical line conductor 152 onto the vertical trunk-conductor *b*. Connection to the said vertical trunk-conductor may be traced from ground G⁷ to the springs 109 and 108 of the pole-changing relay 83, conductor 224, springs 35 99 and 100, conductor 225, springs 107 and 106 of the pole-changing-relay 83, conductor 226, springs 117 and 116 of the vertical switching relay *a* to the vertical trunk-conductor *b*. The effect of grounding the 40 said trunk-conductor *b* each time that the vertical line conductor 152 is grounded will be described. It will be noticed that since the ground circuit between the ground terminal G⁷ and the vertical trunk-conductor 45 *b* comprises springs controlled by the pole-changing relay 83 it is of vital importance that the said relay 83 should not be energized while the vertical impulses desired are transmitted. If the differential relay 82 should not separate the springs 102 and 103, as already stated, it is possible that the relay 83 might become energized over the following circuit when the said springs 100 and 99 are pressed into contact by the vertical line relay 84: from ground G⁷ through the springs 99 and 100, as before, thence through the springs 107 and 106 of the said relay 83, thence through the said relay 83 and springs 103 and 102 of the differential relay 82, conductor 227 to the 50 springs 129 and 124, thence to the rotary trunk-conductor *c* and through the coil of line relay 123 of the selector D through battery B² and to ground G⁷. At any rate the pole-changing-relay 83, when the switching relays *a* and *d* are energized or pulled up, is bridged across the trunk-conductors *b* and *c*, as follows: from the conductor *b* through the springs 116 and 117, thence through the said coil 123, springs 103 55 and 102 of the differential relay 82, conductor 227, springs 120 and 121 to the conductor *c*; and it is necessary that the said conductors *b* and *c* be absolutely separated when the impulses are being transmitted to either side of the trunk-line independently, or else the impulses would pass from one trunk-line to the other. The last result would be very objectionable and would, in fact, render the system inoperative, since 60 grounding both of the trunk-conductors *b* and *c* simultaneously releases the switching apparatus, as will be described. When the rotary line conductor 153 is grounded the rotary line relay 85 of the repeater C together with the differential relay 82 are energized. The energizing current passes from ground G² to the rotary line conductor 153, when the rotary impulse spring 7 is operated, thence to the side switch wiper 173, contact-point 202, conductor 206, rotary line wiper 39, rotary trunk-conductor 208, rotary line relay 85, winding 65 87 of the differential relay 82, springs 119 and 111 of the pole-changing-relay 83 to the battery lead 160, thence from battery B to ground G. Each time that the differential relay 82 is energized the circuit through the pole-changing-relay 83 is destroyed; and when the rotary line relay 85 energizes the 70 springs 98 and 99 are pressed into contact and a ground circuit is established between the ground terminal G⁷ and the rotary trunk-conductor *c*. The connecting circuit is as follows: from ground G⁷ through the 75 springs 109 and 108 to the spring 99, thence through the spring 98, conductor 227 and springs 120 and 121 to the rotary trunk-conductor *c*. The effect of grounding the rotary 80 trunk-conductor *c* each time that the rotary line conductor 153 is grounded will be described hereinafter. The circuit of the preliminary ground impulse that energizes the vertical line relay *g* of the selector D⁴ for causing the vertical magnet *h* to disengage 85 the release-link *j* from the double-dog *k* is as follows: from ground G⁶, as previously stated, to the vertical trunk-conductor *b*, thence to the springs *q* and *r* and conductor *s* 90 to the side switch wiper 228, contact-point 229, conductor 230, vertical line relay *g* to the battery lead 231, thence through battery B³ to ground G⁷. The said vertical line relay upon attracting its armature presses the spring 232 onto the ground spring 233 and 95

thereby energizes the vertical magnet *h*. The current in this new circuit flows from ground *G*⁸ through the springs 233 and 232, conductor 234, private springs 235 and 236 to the vertical magnet *h*, thence to the battery lead 231 and through battery *B*¹ to ground *G*¹. The said vertical magnet then operates the vertical armature *i*, as previously stated, to release the double-dog *k*, whereby the springs *l* and *m* may come into contact. As soon as the said springs engage a connection is established between ground *G*⁹ and the private conductor 215, as previously stated. The two ground impulses delivered to the vertical trunk-conductor *b* from the ground *G*⁷ by the vertical line relay 84 of the repeater *C* causes the vertical line relay *g* of the selector *D*¹ to be energized twice. The circuit beginning with ground *G*⁷ passes through the springs 109 and 108 of the pole-changing-relay 83, the springs 99 and 100 of the line relay 84, thence to the springs 107 and 106 of the pole-changing-relay 83 and springs 117 and 116 of the vertical switching relay *a* to the vertical trunk-conductor *b*, thence to the springs *r* and *q* to the side switch wiper 228 of the selector *D*¹, contact-point 229, conductor 230 and vertical line relay *g* to the battery lead 231 and through battery *B*¹ to ground *G*¹. Said relay *g*, as already described, each time that it is energized, presses the springs 232 and 233 into contact, whereby the vertical magnet *h* is energized each time. Being energized twice the said vertical magnet attracts its armature *i* and causes the pawl *o* to engage the circular teeth *p*, since the pin 127 upon the double-dog *k* is now out of the way of the stock 128 of the pawl *o*, thereby raising the shaft 138 two steps. The line wipers 237 and 238 and the private wiper 239 are raised to the second level of their respective banks 240 and 241 and made ready to be rotated into engagement with the contacts of their respective banks. When the rotary trunk-conductor *e* is grounded by the operation of the rotary line relay 85 the rotary line relay 123 of the selector *D*¹ is then energized. The current for energizing said relay 123 flows from ground *G*⁷ through the springs 109 and 108 of the pole-changing-relay 83, thence through the springs 98 and 99 of the line relay 85 to the conductor 227, thence through the springs 120 and 121 of the rotary switching relay *d* to the rotary trunk-conductor *e*, springs *t* and *u*, conductor *v*, side switch wiper 242, contact-point 243, conductor 244, rotary line relay 123 to the battery lead 231 and through battery *B*¹ to ground *G*¹. The rotary line relay 123 upon attracting its armature forces the springs 245 and 233 into contact, whereby the private magnet 246 is magnetized. The current passes from ground *G*⁸ through the springs 238 and 245, conductors 247 and 248

to the private magnet 246, thence to the battery lead 231 and through battery *B*¹ to ground *G*¹.

When the private magnet attracts and releases its armature 147 the side switch *I* 70 clears the escapement-teeth 249 and 250 and is drawn into second position by the retracting-spring 252. The lug 253 then strikes the cam 254 and retains the finger 251 between the teeth 255 and 249. When the 75 said side switch *I* passes to second position the side switch wiper 256 engages the contact 257, whereby an energizing circuit through the rotary magnet 141 is set up. The current in this circuit flows from 80 ground *G*¹⁰ through the contact-point 257 and side switch wiper 256, conductor 258, rotary magnet coil 259, interrupter springs 149 and 150, rotary magnet coil 260 to the battery lead 231 and through battery *B*¹ to 85 ground *G*¹. Assuming the first nine contacts of the second level of the line bank 240 are busy the first nine contacts of the second level of the private bank 241 will be 90 grounded for well-known reasons. Therefore, when the rotary magnet 141 operates to rotate the private wiper 239 onto the first contact of the second level of the private bank 241 the private magnet 246 will be 95 energized (as described in connection with the first selector *A*) for locking the side switch *I* in second position to maintain the energizing circuit through the rotary magnet 141 until the line wipers 237 and 238 are carried into engagement with the conductors 261 and 262 that lead from the tenth contact of the second level of the line bank 240; and the private wiper 239 is thereby 100 rotated into engagement with the trunk-release-conductor 263 that leads from the tenth contact of the second level of the private bank 241. As soon as connection is established with the trunk the side switch *I* passes to third position and the side switch wipers 228 and 242 engage the contact-points 105 264 and 265, whereby the trunk-conductors *b* and *e* are connected, respectively, with the trunk-conductors 261 and 262. The connecting circuits are as follows: The vertical trunk-conductor *b* and the vertical trunk-conductor 261 are connected through the springs *q* and *r*, conductor *s*, side switch wiper 228, contact-point 264, conductor 266 and vertical line wiper 237. The rotary 110 trunk-conductors *e* and 262 are connected through the springs *t* and *u*, conductor *v*, side switch wiper 242, contact-point 265, conductor 267 and rotary line wiper 238. When the side switch wiper 268 meets the 115 contact-point 269 a guarding potential is established at the tenth contact of the second level of the private bank 241, from ground *G*¹¹ to the contact-point 269, thence 120 through the side switch wiper 268, back-release-relay 270, conductor 271 and private 125 conductor 272. The current in this circuit flows from ground *G*¹¹ through the back-release-relay 270, conductor 271 and private 130 conductor 272 to the tenth contact of the second level of the private bank 241, from ground *G*¹¹ to the contact-point 269, thence through the side switch wiper 268, back-release-relay 270, conductor 271 and private conductor 272.

wiper 239 to the said contact. After the subscriber has established connection with the connector E by way of the trunk-conductors 261 and 262, as described, he operates his dial for the second digit 2. Again the vertical line conductor 152 is grounded twice and the rotary line conductor 153 once. As a result of grounding the former the vertical line relay 75 of the connector E and the differential relay 77 are energized in a series circuit. Each time that the vertical line conductor 152 is grounded, when the impulse spring 4 is operated, the vertical line and differential relays 84 and 82, respectively, of the repeater C are energized, as in previous instances, so that the vertical trunk-conductor b is grounded each time, also causing a flow of current through said vertical line and differential relays 75 and 77 of the connector E. The current flows to the vertical trunk-conductor b, as heretofore, from ground G¹ at the repeater C, and through the springs 99 and 100 to the said trunk-conductor b, thence through the springs q and r of the repeater C to the conductor s, side switch wiper 228, contact-point 264, conductor 266, vertical line wiper 237, vertical trunk-conductor 261, vertical line relay 75, winding 272 of the differential relay 77 to the battery lead 231, and through battery B¹ to ground G¹. When the vertical line relay 75 is energized the line relay spring 273 is pressed onto the ground spring 274, and as a result the vertical magnet 72 is energized. The circuit established extends from ground G¹² through the springs 274 and 273, conductor 275 to the private springs 276 and 277, conductor 278, side switch wiper 279, contact-point 280 to the vertical magnet 72, thence to the battery lead 231 and through battery B¹ to ground G¹. The energization of the differential relay 77 has no significance at this time, but the operation of the vertical magnet 72, since the vertical line relay 75 is energized twice, causes the shaft 59 to be raised two steps and the line wipers 60 and 61 and the private wiper 62 to be placed opposite the first contact of the second level of their respective line and private banks 63 and 64.

When the rotary line conductor 153 is grounded the rotary and differential relays 85 and 82 of the repeater C are also energized, as previously described, whereby the rotary trunk-conductor e is grounded and the rotary line relay 76 and differential relay 77 of the connector are energized. The current through said line and differential relays 76 and 77 flows as follows: from ground G¹ to the springs 99 and 98 of the rotary line relay 85 to the rotary trunk-conductor e, thence through the springs t and u of the repeater C to the conductor v, thence to the side switch wiper 242 of the selector D¹, contact 265, conductor 267, rotary wiper 238, rotary trunk-conductor 262, rotary line relay 76, winding 281 of the differential relay 77, conductor 282 to the springs 283 and 284 of the pole-changing-relay 78, thence to the battery lead 231 and through battery B¹ to ground G¹. The rotary line relay 76 being magnetized the line relay spring 285 is pressed onto the ground spring 274, thereby energizing the private magnet 79 for shifting the side switch J from first to second position. The energizing circuit through the said private magnet 79 is as follows: from ground G¹² through the springs 274 and 283, conductor 286, private magnet 79, conductors 287 and 282, pole-changing-relay 78, springs 283 and 284 to the battery lead 231 and through battery B¹ to ground G¹. The private magnet 79 is thus energized momentarily, and the private armature 288 is attracted and released, whereby the escapement-finger 289 clears the escapement-teeth 290 and 291, so that the side switch J is drawn into second position by the retracting-spring 292. When the side switch passes into second position the side switch wiper 279 leaves the contact-point 280 and engages the contact-point 293 instead, whereby the energizing circuit through the vertical magnet 72 is interrupted and established through the rotary magnet 73 instead. The subscriber then operates his dial for the last digit 0, operating the impulse spring 4 to ground the vertical line conductor 152 ten times, and operating the rotary impulse spring 7 thereafter for grounding the rotary line conductor 153 once. The vertical line relay 84 of the repeater C is energized ten times over circuits that have been traced before, whereby the vertical trunk conductor b is grounded ten times through the ground G¹, and whereby the vertical line relay 75 of the connector E is energized ten times, as previously described. However, when the said relay presses the springs 273 and 274 into contact the circuit that is completed extends through the rotary magnet 73 instead of through the vertical magnet 72. The circuit may be traced from ground G¹² over the same path described in the last instance, as far as the side switch wiper 279, and thence it extends through the contact-point 293 to the rotary magnet 73, battery lead 231, and from battery B¹ to ground G¹. Each time that the rotary magnet 73 is magnetized the rotary armature 294 is attracted so that the pawl 295, by engaging the longitudinal teeth 66, rotates the shaft 59, carrying the line wipers 60 and 61 into engagement with the trunk-conductors 296 and 297 that lead from the tenth terminal of the second level of the line bank 63 and the private wiper 62 into engagement with the private normal conductor 298 leading from the tenth contact of the second level of the private bank 64. Grounding the rotary line con-

ductor 153, as stated, causes the rotary line relay 85 of the repeater C to operate so as to ground the rotary trunk-conductor 6, energizing the rotary line relay 75 of the connector E. Said rotary line relay upon being energized again magnetizes the private magnet 79 so that the escapement-finger 289 is permitted to pass between the escapement-teeth 299 and 300, thereby permitting the side switch J to pass to third position. The side switch in passing to third position places the subscriber's line conductors 152 and 153 in connection with the normal conductors 296 and 297 that lead to the called subscriber's station. The subscriber's extended line conductor 261 is connected with the vertical normal conductor 296 through the condenser 301, conductor 306, conductor 307, ringer-relay springs 308 and 309, side switch wiper 310, contact-point 311, conductor 312 and rotary line wiper 61.

When the side switch carries the wiper 312 into engagement with the grounded contact-point 313, a guarding potential is established at the private wiper 62 for protecting the seized line. This guarding potential is set up from ground G^1 through the side switch wiper 312, conductor 314 to the private wiper 62, thence to the tenth contact 315 of the second level of the private bank 64. Furthermore, when the wiper 312 engages the contact point 313 a circuit is closed through the bridge-cut-off relay 315 at the selector A of the called subscriber's line.

The current passes from the said private wiper 62 to the private normal conductor 298, thence through the switch-shaft springs 316 and 317 and bridge-cut-off-relay 315 to the battery lead 231 and through battery B to ground G^1 . The said bridge-cut-off-relay then operates the springs 318, 319 and 320 and disconnects the vertical and rotary line-relays 321 and 322 from the battery lead 231, thus also breaking the connection between the normal conductors 296 and 297 that is normally maintained through the said relays 321 and 322, for well-known reasons. The calling subscriber having established connection with the called line may then signal the called subscriber by pressing his signaling button 30. By pressing the signaling button 30 the spring 31 is pressed onto the contact point 33 and a ground circuit is thereby established from the ground terminal G^2 through the ground springs 14 and 17 to the contact-point 33, thence through the spring 31 and springs 27 and 28 to the vertical line conductor 152. Grounding the vertical line conductor in a well-known manner causes the vertical line relay

75 of the connector E to be operated, which latter, as will be described, when the side switch J is in third position, in turn causes the ringer-relay 80 to be operated.

It may be stated at this juncture that if the called line is busy at the time that the rotary line conductor 153 is grounded, and when the dial is operated for the last digit, then instead of the side switch J passing to third position and thereby connecting the calling subscriber's line with the called subscriber's line the connector E is released and a busy-signal is sent to the calling subscriber. The operation, as is well-known, is as follows: If the called line is busy by reason of either calling or being called a guarding potential appears at the tenth contact of the second level of the private bank 64. In the former case, when the normal post arm 323 rises, the closure of connection between the switch-shaft springs 324 and 316 connects the said contact-point over the private normal conductor 298 with the ground terminal G^1 . In the latter case, whatever connector is connected with the line has its side switch wiper (like the side switch wiper 312) connected with a ground similar to the ground G^1 , so that the guarding potential is established through the private wiper (similar to the private wiper 62) to a multiple contact of the private normal conductor 298 and, therefore, to the tenth contact of the second level of the private bank 64. The said tenth contact when grounded will cause the connector to be released at the instant that the private magnet 79 attracts its armature 288 when the rotary line conductor 153 is grounded, as described. The said private magnet 79 upon attracting the said armature 288 closes a circuit through the release magnet 74 of the said connector E.

The energizing circuit is as follows: from ground G^1 by either of the paths described to the tenth contact of the second level of the private bank 64 to the private wiper 62, conductor 314, side switch wiper 312, contact-point 315, since the side switch is in second position, conductor 323, private springs 327 and 328, conductors 329 and 330, release-magnet 74, conductor 331 and, since the differential relay 77 is now energized, through the differential relay springs 332 and 333 to the battery lead 231 and through battery B to ground G^1 . The release magnet 74 then attracts its armature 334, which latter then strikes the double-dog 335 at a point to the right of the bearings 336, restoring the side switch J to first position, driving the lug 337 of the double-dog 335 under the aperture at the end of the release-link 338, thereby locking the said double-dog. The rotary and vertical locking dogs 339 and 340 being withdrawn from the shaft 39 the said shaft then rotates and falls to normal position, as is well-known. Then when the subscriber

- presses his signaling button, as described, thereby grounding the vertical line conductor 152, the vertical line relay 75 is energized so that, since the side switch J is now in first 5 position, the vertical magnet 72 raises the switch-shaft 59. The switch-shaft springs 341 and 342 then close into contact and a busy signaling current is transmitted from the busy coil 343 to the subscriber's station.
- 10 The current does not reach there direct but in the following manner: The flow of current is first established from the coil 343 through the springs 341 and 342 to the side switch contact-point 344, thence through the side 15 switch wiper 310, ringer-relay springs 309 and 308, conductor 307, condenser 306, rotary trunk-conductor 262, rotary line wiper 268 of the selector D¹, contact-point 265, side switch wiper 242, rotary trunk-conductor e,
- 20 repeater rotary switching relay springs u and t, rotary trunk-conductor e, repeater rotary switching relay springs 121 and 120, winding 92 of the repeater coil 89, condenser 94, winding 90 of the repeater coil 88, vertical 25 cal switching relay springs 117 and 116 to the vertical trunk-conductor b, repeater vertical switching relay springs g and r, conductor s, side switch wiper 228, contact-point 264, conductor 266, vertical line wiper 237, vertical 30 trunk-conductor 261, vertical line relay 75, winding 272 of the differential relay 77 to the battery lead 231 and through battery B¹ to ground G¹. At the repeating coils 88 and 89 the busy current is induced in the windings 91 and 93, passing thence from the said windings over the heavy conductors shown in Fig. 1, through the primary winding 20 of the induction-coil 19 at the calling station. A current is in turn induced in the secondary 40 winding 21 of the induction-coil 19 which in turn affects the receiver 22. The subscriber upon hearing the busy-signal restores his receiver 22, which will then cause the release-springs 34, 35 and 36 to come together,
- 45 grounding the vertical and rotary line conductors 152 and 153 simultaneously. The circuit to each one of the said conductors may be traced from ground G² and through the ground springs 14 and 17 to the release-spring 34, thence through the springs 35 and 36 to the respective conductors 152 and 153. Current will flow through the vertical and rotary line-relays 84 and 85 of the repeater C and through the windings 86 and 87 of the differential relay 82 simultaneously. The said line relays 84 and 85 will be energized together with the differential relay 82. When said line relays 84 and 85 press the springs 98, 99 and 100 into contact, the vertical and rotary trunk-conductors b and e are grounded simultaneously from ground G² through the pole-changing-relay springs 109 and 108 to the ground spring 99, thence through the spring 100 on one side and pole-changing-relay springs 107 and 106 to the vertical trunk-conductor b, and from the said spring 99 and spring 98 on the other side through the conductor 227 to the rotary trunk-conductor e. The effect of grounding both of said conductors simultaneously will be desired. Returning to the line relays 84 and 85 it will be seen that not only the springs 98, 99 and 100 are brought into contact, but that the springs 97 and 101 come together also. Furthermore, the differential relay 82 being energized the differential relay springs 104 and 105 are in contact at the same time. As a result a circuit is established that contains the resistance-coil 96 of the repeater C in series with the back-release-relay 49 of the selector A. Tracing said circuit from G² at the selector A it extends to the contact-point 204, side switch wiper 197, conductor 196, back-release-relay 49, conductor 195, private wiper 40, thence 50 through the line relay springs 101 and 97, resistance-coil 96, differential relay springs 105 and 104 to the battery lead 160, thence through battery B to ground G. The said back-release-relay 49 upon energizing attracts its armature and forces the back-release relay springs 345 and 346 into contact, whereby the release-magnet 45 of the first-selector A is energized. Said release-magnet attracts its armature 347, which latter then 55 thrusts the release-link 168 forward to engage the lug 170. Said release-magnet 45 remains energized as long as the vertical and rotary line conductors 152 and 153 are grounded by the operation of the said release springs 34, 35 and 36.
- With further reference to the simultaneous grounding of the vertical and rotary trunk-conductors b and e, it will be seen that energizing currents are established through 60 the vertical and rotary line relays 75 and 76 of the connector E, over the same circuits by which the said relays have been energized heretofore. Not only are the said relays 75 and 76 energized, but the differential relay 77 is energized as well, since the flow of current through the windings 272 and 281 reinforce each other in magnetizing said relay. The simultaneous energizing of the said line and differential relays completes an 65 energizing circuit through the release-magnet 74 of the connector, in series with the back-release-relay 270 of the selector D¹. This circuit is completed by the bringing into contact of the trunk-release-springs 348 and 349 of the line relays 75 and 76 at the same time that the differential relay springs 332 and 333 are in contact. Beginning with the ground terminal G¹¹ at the side switch I of the selector D¹ 70 the circuit extends from the contact-point 269, side switch wiper 268, back-release-relay 270, private wiper 288, trunk-release-conductor 263, trunk-release-springs 348 and 349, release-magnet 74, differential relay 75

springs 332 and 333 to the battery lead 231 and through battery B¹ to ground G¹. The connector release-magnet 71 attracts the release-armature 334, restoring the switch shaft 59, as already explained, but the magnets 74, 75, 76 and 77 remain energized for the time being. Together with the said release-magnet 74, the back-release relay 270 of the selector D¹ energizes also, and the back-release-relay springs 350 and 351 close a magnetizing circuit through release-magnet 214 of the said switch D¹. The established circuit for admitting current begins with ground G¹ and extends through the springs 350 and 351 and through the release-magnet 214 to the battery lead 231, thence through battery B¹ to ground G¹. The release-magnet 45 of the selector A pulls up to latch the double-dog 171 with the link 368, but stays magnetized for the time being. As soon as the subscriber's release-springs 34, 35 and 36 are out of contact the vertical and rotary line relays 84 and 85 of the repeater 82 de-energize as the first result thereof. The energizing circuit through the back-release-relay 49 of the selector A is broken at the trunk-release-springs 101 and 97 of the repeater C and also at the differential relay springs 104 and 105. The restoration of the back-release-relay 49 causes a restoration of the release-magnet 45, at which time the retracting-spring 332 restores the side switch H and the double-dog 171, and at the same time the switch-shaft 37 is restored, separating the switch springs 131 and 132 and thereby removing the guarding potential from the connector banks, whereby another subscriber may then call the subscriber X. When the private wiper 40 of the selector A leaves the trunk-release-conductor 209 the energizing circuit through the vertical switching relay *a* of the repeater C is cut off, at which time the said relay regains its normal position, restoring the vertical line relay *c* of the switch D into connection with the vertical trunk-conductor *b*, destroying at the same time the energizing circuit through the rotary switching relay *d*. The latter relay upon de-energizing restores the rotary line relay *f* of the selector D into connection with the rotary trunk-conductor *e*. The line relays 84 and 85 destroy the energizing circuit through the back-release-relay 49, as stated, and the ground connection to the vertical and rotary trunk-conductors *b* and *c* is removed. As a result there follows, of course, the de-energization of the vertical and rotary line relays 75 and 76 and the differential relay 77 of the connector E, which relays upon being de-energized destroy the energizing circuit through the release-magnet 74, restoring the said connector. Since the back-release-relay 270 is in the same circuit with the release-magnet 74 the said release-relay 270 also deenergizes,

causing in turn the de-energization of the release-magnet 214 of the switch D¹. When the release-magnet 214 demagnetizes the retracting-spring 133 then restores the shaft 138, the side switch I and the double dog *k*. The restoration of the said double-dog *k* in turn permits the disengagement of connection between the springs *l* and *m*, whereby the guarding potential at the second exchange is removed from the trunk-line, and the said spring *l* is restored into connection with the contact-point 134, leaving the said switch D¹ fully restored.

In the event that the calling subscriber establishes connection with the called subscriber, the signaling button 30 is pressed and the vertical line relay 75 energized. It was stated that the said relay 75 being thus energized while the side switch J is in third position, a circuit is closed through which the ringer-relay 80 is energized. The energizing circuit for said ringer-relay begins from ground G² and extends through the springs 274 and 273 to the side switch wiper 279, thence through the contact-point 333 to the ringer-relay 80, through the conductor 354, differential relay springs 332 and 333, since the differential relay 77 is now energized, and to the battery lead 231 and through battery B¹ to ground G¹. The said ringer-relay 80 then presses the springs 309 and 355 onto the springs 356 and 357, bridging the generator 81 across the line of the called subscriber. The current is then sent through the ringer 358 at said station over the following circuit: from ringer generator 81 to the side switch wipers 303 and 310 through the contact-points 304 and 311 and line wipers 60 and 61, normal conductors 296 and 297 and subscriber's line conductors 359 and 360 to the ringer 358. The subscriber upon hearing the signal removes his receiver 361, breaking the ringer circuit at the springs 362 and 363 and closing the line circuit at the springs 364 and 365. Closing the said circuit through the said springs sends a flow of current through the windings 366 and 367 of the back-bridge-relay 78, causing the said relay to pull up. The circuit is as follows: from ground G² at the side switch of the connector through the winding 367 of the back-bridge-relay 78, conductor 307, ringer-relay springs 308 and 309, side switch wiper 310, contact-point 311, conductor 312^a, wiper 61, normal conductor 297, line conductor 360, primary winding 368 of the induction-coil 369, transmitter 370, springs 364 and 365 to the vertical line conductor 359, thence through the vertical normal conductor 296, line wiper 60, conductor 305, contact-point 304, side switch wiper 303, through the winding 366 of the back-bridge-relay 78, pole-changing-relay springs 371 and 333 to the battery lead 231 and through battery B¹ 130.

- to ground G^1 . The said relay 78 upon operating presses the spring 283 onto the spring 372 after separating it from the spring 284 and establishes, therefore, an energizing circuit through the pole-changing-relay 83 of the repeater C. The engagement of the springs 283 and 372 sends a flow of current from the ground terminal G^{13} at the side switch J of the connector E through the said springs 372 and 283, thence through the winding 281 of the differential relay 77 and through the rotary line relay 76 to the trunk-conductor 262, rotary line wiper 238 of the switch D¹, contact-point 265, conductor v , rotary switching relay springs u and t , rotary trunk-conductor c , rotary switching relay springs 121 and 120, conductor 227, through the differential relay springs 102 and 103, pole-changing-relay 83, vertical switching relay springs 117 and 116 to the vertical trunk-conductor b , thence through the vertical switching relay springs q and r of the repeater C, conductor s , side switch wiper 228, contact-point 264, vertical line relay 75, winding 272 of the differential relay 77 to the battery lead 231, and through battery B¹ to ground G^1 . As soon as the pole-changing-relay 83 pulls up, among other things, the spring 110 is separated from the non-grounded battery spring 111 and pressed onto the grounded battery spring 109 for sending a flow of current through the transmitter of the calling subscriber. The path of the current may be traced from the ground terminal G^1 through the springs 109 and 110, thence through the winding 87 of the differential relay 82, rotary line relay 85, rotary line wiper 39 of the selector A, contact-point 203, side switch wiper 173, rotary line conductor 153, primary winding 29 of the induction-coil 19, transmitter 18 to the vertical line conductor 162, thence through the side switch wiper 164, contact-point 202, vertical line wiper 38, vertical trunk-conductor 207 to the vertical line relay 84, thence through said relay and the winding 86 of the differential relay 82 to the battery lead 169 and through battery B to ground G^1 .
- Both subscribers' transmitters being provided with talking battery current the two subscribers may communicate with each other over the heavily marked conductors shown clearly in Figs. 1, 2 and 3. The voice currents generated by the transmitter 18 pass to the vertical trunk-conductor 152 and thence through the side switch wiper 154 and vertical line wiper 38 to the winding 91 of the repeating-coil 88, thence through the condenser 95, winding 93 of the repeating-coil 89, back through the rotary line wiper 39 and side switch wiper 173 to the rotary line conductor 153, and through the primary winding 20 to the transmitter 18. Said voice currents are induced into the windings 90 and 92 of the repeating-coils 88 and 89 and are then transmitted through the vertical switching relay springs 117 and 116 to the vertical trunk-conductor b , thence through the springs q and r at the repeater C, conductor s and side switch wiper 228 of the switch D¹ to the vertical line wiper 237, vertical trunk-conductor 261, condenser 301 of the connector E, side switch wiper 303, vertical line wiper 60, vertical normal and line conductors 296 and 359 to the transmitter 370, thence through the primary winding 368 and rotary line and normal conductors 360 and 297 to the rotary line wiper 61, side switch wiper 310, ringer-relay springs 309 and 208, condenser 306, rotary trunk-conductor 262, rotary line wiper 238, side switch wiper 242, conductor v , rotary switching relay springs u and t , rotary trunk-conductor c , rotary switching relay springs 121 and 120 and to the coil 92 of the repeating-coil 89. During conversation not only are the pole-changing-relay 83 at the repeater C and the back-bridge-relay 78 at the connector E energized, but also the line relays 84 and 85 at the repeater C, as well as the line-relays 75 and 76 at the connector E. The differential relay 82 at the repeater C and the differential relay 77 at the connector E, however, are not energized, because the currents that are flowing through the windings of said relays oppose each other. The object in energizing the pole-changing-relay 83 is not only to shift the spring 110 from the non-grounded to the grounded pole of the battery, as described, but also to break connection between the ground terminal G^1 and the ground spring 99, controlled by the line relays 84 and 85. This connection is broken between the springs 109 and 108 of the said pole-changing-relay 83. It is essential that this connection be broken, or else the vertical and rotary trunk-conductors b and c would be grounded while the relays 84 and 85 are energized, and it would be impossible to energize the relay 83. It is also necessary to provide the springs 106 and 107 at the pole-changing-relay 83 to disconnect the line relay spring 100 from the pole-changing-relay 83, or else the said relay would be short-circuited when the line relays 84 and 85 are energized, and it would be impossible to energize said pole-changing-relay 83. After the subscribers are through talking the calling subscriber may release the switching apparatus by restoring his receiver to the switch-hook and again grounding the vertical and rotary line conductors simultaneously. Since the rotary line conductor 153 is already grounded at G^1 at the repeater C, grounding the said rotary line conductor at the ground release-spring 34 will now short-circuit all windings between 125 and 136.

the said release-spring 34 and the said ground point G¹, and thus cut off the flow of current in that section of the circuit. The relays that are thus affected are the rotary line relay 85 and the winding 87 of the differential relay 82. The rotary line relay 85 becomes deenergized, and the trunk-release-spring 97 leaves the trunk-release-spring 101, but the differential relay 82 on the contrary energizes, since current is now flowing only through the winding 86. The energizing of the differential relay 82 breaks the energizing circuit through the pole-changing-relay 83, which circuit, as explained, comprises the differential relay springs 102 and 103. Not only is the pole-changing-relay 83 deenergized, but the vertical and rotary line relays 75 and 76 at the connector are also deenergized, since the said relays are in the same energizing circuit with the pole-changing-relay 83. As soon as the said pole-changing-relay 83 deenergizes, among other things, the spring 109 reengages the spring 108, providing a ground connection to the line relay spring 99 from ground G¹. At the same time the pole-changing-relay springs 107 and 106 close the connection between the line relay spring 100 and the vertical trunk-conductor b, grounding the said vertical line relay 75 and b, energizing the vertical line relay 75 of the connector E, differential relay 77 of the connector E. The differential relay 77 becoming energized forces the springs 371 and 323 apart, thereby destroying the energizing circuit through the back-bridge-relay 78, which circuit comprises the said springs 323 and 371. When the said back-bridge-relay 78 deenergizes the spring 283 is restored into normal engagement with the non-grounded terminal of battery B¹ and removes the ground connection through the rotary line relay 76 to the rotary trunk-conductor 262, which has already been described; also the energizing current is cut off from the transmitter 370 of the called subscriber.

As soon as the pole-changing-relay 83 permits the spring 110 to engage the spring 111, as previously stated, the rotary line relay 85 is reenergized, since the said relay through the winding 87 of the differential relay 82 is reinstated in connection with the non-grounded terminal of battery B. It will be seen, however, that now the current through the winding 87 of the differential relay 82 assists the current in the coil 86 to magnetize the said differential relay. As soon as the rotary line relay is energized the trunk-release-spring 97 reengages the vertical release-spring 101, and since the differential relay springs 105 and 104 are in contact the relay springs 105 and 104 are in contact the release circuit for the first-selector A¹ comprising the resistance coil 96 and the release-relay 40 is established, the release-relay 40 being established when the subscriber releases the subscriber's receiver after partition 55

busy signal), so that the release-magnet 45 of the first-selector A is energized. Also, since the pole-changing-relay 83 is in normal condition, the energizing of the rotary line relay 85 grounds the rotary trunk-conductor c over circuits that have been previously traced, the ground connection being established through ground G¹ at the repeater C. As a result the rotary line relay 76 of the connector reenergizes, and a reinforcing flow of current is then reestablished through the winding 281 of the differential relay 77, as described in connection with the differential relay 82. As soon as the rotary line relay 76 energizes the trunk-release-springs 318 and 319 reengage, and since the differential relay 77 is energized, and, therefore, since the differential relay springs 332 and 333 are in contact, the release circuit comprising the release-magnet 74 of the connector and back-release-relay 270 of the selector D¹ is once more completed. Of course, the connector is at once released, and when the private wiper 62 leaves the private normal conductor 298 the energizing circuit through the bridge-cut-off-relay 315 of the first-selector A¹ is destroyed so that the springs 318, 319 and 320 regain their normal condition, restoring the selector A¹. The back-release-relay 270 of the selector D¹, of course, causes the release-magnet 214 to become magnetized and remain so for the time being. However, as soon as the release-springs 34, 35 and 36 at the substation X disengage all the energized relays and magnets deenergize, as in the previous release which has been described, so that all the switches are restored to normal condition. It will be evident that if the called subscriber had restored his receiver first the back-bridge-relay 78 of the connector E would then have deenergized and talking battery current would have been removed from the calling and called subscribers' lines, leaving the apparatus in the same condition that it was just before the called subscriber removed his receiver. In that case if the calling subscriber had restored his receiver the line conductors would have been grounded simultaneously and the switches would have been released in the same manner and over the same circuits that were described when he released after receiving the busy-signal; the only difference, however, being that the connector-shaft 59 being both raised and rotated it is first rotated to normal rotary position and then lowered to normal vertical position. Also, the energizing circuit through the bridge-cut-off-relay 315 of the first-selector A¹ would have been broken in the same manner as would be the case if the called subscriber had answered. It will be understood, of course, and it should be perfectly clear, that if a call were to come from the central 52 to the central 126 when the subscriber released after partition 55

- #1 the vertical and rotary switching relays 273^a and 274^c of the repeater C¹ would take the place of the vertical and rotary switching relays *a* and *d* of the repeater C, per- 5 forming the same work that has already been described in connection with said relays. The repeater C¹ would perform the operations described for the repeater C and vice versa. The vertical and rotary line re- 10 lays *g* and 123 of the second-selector D¹ instead of the vertical and rotary line relays *c* and *f* of the selector D would be discon- nected from the trunk-line-conductors *b* and *c*. The vertical and rotary normal con- 15 ductors 374 and 375 and the private normal conductor 376 lead to the connector line and private banks and terminate in contacts that correspond to the line that leads to the sub- station X. Said line and private normal 20 conductors 374, 375 and 376 correspond to the similar conductors 296, 297 and 298 leading from the connector E at the substation #2220. It will be evident that the magnets of the repeater C may be wound to any suf- 25 ficient resistance, but good results are obtained by having the line relays 84 and 85 each wound to 100 ohms each; each of the windings of the differential relay 82 to two hundred and fifty ohms; the pole-changing- 30 relay 80 to five hundred ohms; and the switching relays *a* and *d* to thirteen hundred ohms each. With reference to Fig. 7, it may be stated that the circuits there 35 shown are comprised in Figs. 1, 2 and 3. The selectors herein referred to may be of the general type disclosed in Patent No. 815,321, granted March 13, 1906, to Keith, Erickson & Erickson. The connectors here- 40 in referred to may be of the general type disclosed in Patent No. 815,176, granted March 13, 1906, to Keith, Erickson & Erickson. In certain respects it will be seen that the repeaters herein shown and described are 45 in many respects an improvement on the repeater covered by my prior application Serial No. 294,563, filed by me in the United States Patent Office on the fourth day of January, 1906.
- From the foregoing it will be seen that I 50 provide a common battery telephone exchange system in which provision is made for automatically trunking in opposite directions over one and the same trunk-line. It will also be seen that the automatic 55 means for trunking in one direction over a trunk-line are separate and distinct from the automatic means for automatically trunking in the opposite direction over the same trunk-line. In other words, the repeater C 60 is separate and distinct from the selector D, and the same is true of the repeater C¹ and the selector D¹. The repeater C and the selector D are adapted to coöperate for the purpose of automatically trunking in 65 one direction over the trunk-line composed
- of the parallel line-conductors *b* and *c*, and the repeater C¹ is adapted to coöperate with the selector D in trunking in the opposite direction over the same trunk-line-conductors. Thus I provide a telephone exchange system 70 in which the current both for charging the subscribers' microphone transmitters and operating the automatic trunking and connecting switches is all supplied from a common battery or batteries located at the ex- 75 change or central station, or at the different central stations if trunking is desirable be- 80 tween exchanges, and in which trunking is carried on in opposite directions over the same trunk-lines. Other features and points 85 of advantage will be obvious to those skilled in the art, and as changes and modifications and different uses can be made of different features of my invention without departing from the spirit thereof, I do not limit myself to the exact construction shown and described.
- What I claim as my invention is:—
1. In a telephone exchange system, telephone lines, a trunk-line, automatic means 90 for automatically trunking in one direction over said trunk-line, automatic means for automatically trunking in the opposite direction over said trunk-line, and a central- 95 ized source of current supply for both operating said automatic means and supplying talking current to the said telephone lines.
  2. In a telephone exchange system, telephone lines, a two-way trunk-line, a repeater 100 and a selector for automatically trunking in one direction over said trunk-line, another repeater and a selector for automatically trunking in the opposite direction over said 105 trunk-line, a battery for supplying current for operating said repeaters and selectors, and subscribers' transmitters adapted to receive talking current over the said telephone lines from said battery.
  3. In a telephone exchange system, a two- 110 way trunk-line composed of but two parallel metallic conductors, one-way trunk-lines each comprising three parallel metallic conductors, repeaters and selectors for connect- 115 ing a three-conductor trunk with the two- 115 way trunk to automatically extend a trunk- 120 connection over the latter in one direc- 120 tion, repeaters and selectors for connecting a three-conductor trunk with the two-way 125 trunk-line to automatically extend a trunk- 125 connection over the latter in the oppo- site direction, telephone lines each comprising but two parallel metallic conductors, and common battery means for supplying both talking and switching current to the 125 said telephone lines.
  4. In a telephone exchange system, a two- 130 way trunk-line, automatic means including a repeater for automatically trunking over said trunk-line in one direction, and auto- 130

automatic means including a repeater for automatically trunking over said trunk-line in the opposite direction, the means for trunking in one direction being separate and distinct from the means for trunking in the other direction, but both means being allotted to and connected with the ends of said trunk-line.

5. In a telephone exchange system, a two-way trunk-line, a repeater and a selector allotted to and connected with one end of said trunk-line, another repeater and selector allotted to and connected with the other end of said trunk-line, and means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors.

6. In a telephone exchange system, telephone lines, one or more common batteries for supplying talking current to said telephone lines, a two-way trunk-line, automatic switches, means for transmitting switch operating electrical impulses over said trunk-line in one direction to establish connection with a called telephone line, and means for transmitting switch operating electrical impulses over said trunk-line in the opposite direction to establish connection with a called telephone line.

35 7. In a telephone exchange system, an automatic telephone exchange, another automatic telephone exchange, telephone lines connecting with each exchange, common batteries for supplying talking current to the telephone lines, a two-way trunk-line extending from one exchange to the other, and automatic means at each exchange for trunking in opposite directions over said trunk-line, whereby a subscriber of either exchange may employ said trunk-line for calling a subscriber of the other exchange.

8. In a telephone exchange system, a repeater comprising means for repeating voice currents, means for repeating switch operating impulses, and a talking circuit, said repeater being also provided with a pair of switching relays, one relay controlling the other, and each relay controlling the talking circuit, and a battery with connections for supplying talking current through the repeater to the talking circuit.

9. In a telephone exchange system, a talking circuit, means for producing voice currents in said circuit, means for producing switch operating impulses in said circuit, switches to be operated by said impulses, a repeater provided with a pair of relays controlling the talking circuit, one relay controlling the other, said repeater comprising means for repeating voice currents,

means for repeating switch operating impulses, and a battery with connections for supplying talking current through the repeater to the talking circuit.

10. In a telephone exchange system, a talking circuit, means for inductively dividing said talking circuit, automatic switches, means for producing voice currents in said talking circuit, means for transmitting switch operating electrical impulses over said circuit, relays for repeating switch operating electrical impulses from one side of said inductive means to the other, a pair of relays controlling the circuit at one side of said inductive means, one relay controlling the other, and a battery with connections for supplying talking current to the talking circuit.

11. In a telephone exchange system, a pair of trunk-conductors, a pair of line relays provided with a grounded spring, a calling subscriber's telephone line, a battery for supplying talking current to said line, and a pole-changing-relay controlling the supply of talking current to the said telephone line, controlling the ground circuit to the said ground spring, and provided with means for preventing establishment of a short-circuit between said trunk conductors when the line relays are simultaneously energized.

12. In a telephone exchange system, in combination with a line circuit, a plurality of trunk lines divided into groups, an automatic switch for connecting with one of said trunks for extending a connection from said line circuit, said switch including a double dog, a release-link, a release magnet for operating said link, circular ratchet-teeth, a pawl engaging said teeth, a vertical magnet for operating said pawl, and a pin carried by said double-dog adapted to control the said vertical pawl, the said pawl, when the magnet is energized, engaging the said teeth until after the release-link releases the said double-dog, whereby said line circuit is restored to normal by the deenergizing of said release magnet.

13. In a telephone exchange system, in combination with a line circuit, a selector provided with line relays and a vertical magnet controlled thereby, a vertical ratchet-pawl having a pin, ratchet-teeth, a double-dog provided with a pin, and a spring for causing said first-mentioned pin to engage said last-named pin, whereby the first vertical impulse received over said circuit by said selector is prevented from producing vertical motion therein.

14. In a telephone exchange system, in combination with a line circuit, a selector provided with line relays and a vertical magnet controlled thereby, a vertical ratchet-pawl, ratchet-teeth, a double-dog, and means on the double-dog for engaging said

vertical pawl whereby the first vertical impulse received over said circuit by said selector is prevented from producing vertical motion therein.

5 15. In a telephone exchange system, the combination of telephone lines, a trunk-line, automatic means for automatically trunking in one direction over said trunk-line, automatic means for automatically trunking

10 in the opposite direction over said trunk-line, a centralized source of current supply for both operating said automatic means and supplying talking current to the said telephone lines, a centralized source of ringing current, and means including a calling subscriber's switch for controlling the supply of ringing current to the called subscriber's station.

16. In a telephone exchange system, the 20 combination of telephone lines, a two-way trunk-line, a repeater and a selector for automatically trunking in one direction over said trunk-line, another repeater and a selector for automatically trunking in the op-

25 posite direction over said trunk-line, a battery for supplying current for operating said repeaters and selectors, subscriber's transmitters adapted to receive talking current over the said telephone lines from said battery, a 30 centralized source of ringing current, and means including a calling subscriber's switch for controlling the supply of ringing current to the called subscriber's station.

17. In a telephone exchange system, the 35 combination of a two-way trunk-line composed of but two parallel metallic conductors, one-way trunk-lines each comprising three parallel metallic conductors, repeaters and selectors for connecting a three-con-

40 ductor trunk with the two-way trunk to automatically extend a trunking connection over the latter in one direction, repeaters and selectors for connecting a three-con-

45 ductor trunk with the two-way trunk-line to automatically extend a trunking connection with the latter in the opposite direction, telephone lines each comprising but two parallel metallic conductors, common battery means for supplying both talking

50 and switching current to the said telephone lines, a centralized source of ringing current, and means including a calling subscriber's switch for controlling the supply of ringing current to the called subscriber's station.

55 18. In a telephone exchange system, the combination of a two-way trunk-line, automatic means for automatically trunking over said trunk-line in one direction, automatic

60 means for automatically trunking over said trunk-line in the opposite directions, the means for trunking in one direction being separate and distinct from the means for trunking in the other direction, but both means being allotted to and connected with

5 the ends of said trunk-line, a centralized

source of ringing current, and means including a calling subscriber's switch for controlling the supply of ringing current to the called subscriber's station.

19. In a telephone exchange system, the 70 combination of a two-way trunk-line, a repeater and a selector allotted to and connected with one end of said trunk-line, another repeater and selector allotted to and connected with the other end of said trunk-line, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors, a centralized source of ringing current, and means including a calling subscriber's switch for controlling the supply of ringing current to the called subscriber's station.

20. In a telephone exchange system, the 90 combination of telephone lines, one or more common batteries for supplying talking current to said telephone lines, a two-way trunk-line, automatic switches, means for transmitting switch operating electrical impulses over said trunk-line in one direction 95 to establish connection with a called telephone line, means for transmitting switch operating electrical impulses over said trunk-line in the opposite direction to establish connection with a called telephone 100 line, a centralized source of ringing current, and means including a calling subscriber's switch for controlling the supply of ringing current to the called subscriber's station.

21. In a telephone exchange system, the 105 combination of an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, whereby a subscriber of either exchange may employ said trunk-line 110 for calling a subscriber of the other exchange, a centralized source of ringing current, and means including a calling subscriber's switch for controlling the supply of ringing current to the called subscriber's 115 station.

22. In a telephone exchange system, the combination of a repeater comprising means for repeating voice currents, means for repeating switch operating impulses, and a 125 talking circuit, said repeater being also provided with a pair of switching relays, one relay controlling the other, and each relay controlling the talking circuit, a battery with connections for supplying talking cur- 130

rent through the repeater to the talking circuit, a centralized source of ringing current, and means including a calling subscriber's switch for controlling the supply of ringing current to the called subscriber's station.

- 5 23. In a telephone exchange system, the combination of a talking circuit, means for producing voice currents in said circuit, means for producing switch operating impulses in said circuit, switches to be operated by said impulses, a repeater provided with a pair of relays controlling the talking circuit, one relay controlling the other, said repeater comprising means for repeating voice currents, means for repeating switch operating impulses, a battery with connections for supplying talking current through the repeater to the talking circuit, a centralized source of ringing current, and means including a calling subscriber's switch for controlling the supply of ringing current to the called subscriber's station.

24. In a telephone exchange system, the combination of a talking circuit, means for inductively dividing said talking circuit, automatic switches, means for producing voice currents in said talking circuit, means for transmitting switch operating electrical impulses over said circuit, relays for repeating switch operating electrical impulses from one side of said inductive means to the other, a pair of relays controlling the circuit at one side of said inductive means, one relay controlling the other, a battery with connections for supplying talking current to the talking circuit, a centralized source of ringing current, and means including a calling subscriber's switch for controlling the supply of ringing current to the called subscriber's station.

- 45 25. In a telephone exchange system, the combination of a pair of trunk-conductors, a pair of line relays provided with a grounded spring, a calling subscriber's telephone line, a battery for supplying talking current to said line, a pole-changing relay controlling the supply of talking current to the said telephone line, controlling the ground circuit to the said ground spring, and provided with means for preventing establishment of a short-circuit between said trunk-conductors when the line relays are simultaneously energized, a centralized source of ringing current, and means including a calling subscriber's switch for controlling the supply of ringing current to the called subscriber's station.

- 60 26. In a telephone exchange system, the combination of telephone lines, a trunk-line, automatic means for automatically trunking in one direction over said trunk-line, automatic means for automatically trunking in the opposite direction over said trunk-line, a centralized source of current supply for both operating said automatic means and

supplying talking current to the said telephone lines, a connector provided with relay-coils, and connections by which talking current is supplied through said connector relay-coils to the called subscriber's station. 70

75 27. In a telephone exchange system, the combination of telephone lines, a two-way trunk-line, a repeater and a selector for automatically trunking in one direction over said trunk-line, another repeater and a selector for automatically trunking in the opposite direction over said trunk-line, a battery for supplying current for operating said repeaters and selectors, subscribers transmitters adapted to receive talking current over the said telephone lines from said battery, a connector provided with relay-coils, and connections by which talking current is supplied through said connector relay-coils to the called subscriber's station. 85

90 28. In a telephone exchange system, the combination of a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection with the latter in the opposite direction, telephone lines each comprising but two parallel metallic conductors, common battery means for supplying both talking and switching current to the said telephone lines, a connector provided with relay-coils, and connections by which talking current is supplied through said connector relay-coils to the called subscriber's station. 100

105 29. In a telephone exchange system, the combination of a two-way trunk-line, automatic means for automatically trunking over said trunk-line in one direction, automatic means for automatically trunking over said trunk-line in the opposite direction, the means for trunking in one direction being separate and distinct from the means for trunking in the other direction, but both means being allotted to and connected with the ends of said trunk-line, a connector provided with relay-coils, and connections by which talking current is supplied through said connector relay-coils to the called subscriber's station. 110

115 30. In a telephone exchange system, the combination of a two-way trunk-line, a repeater and a selector allotted to and connected with one end of said trunk-line, another repeater and selector allotted to and connected with the other end of said trunk-line, means for controlling said repeaters and selectors, the selector at one end of the trunk-line being adapted to coöperate with 120

- the repeater at the other end for trunking in one direction, and the other repeater and selector being adapted for trunking in the opposite direction, said repeaters being units in themselves and separate and distinct from said selectors, a connector provided with relay-coils, and connections by which talking current is supplied through said connector relay-coils to the called subscriber's station. 5
- 10 31. In a telephone exchange system, the combination of telephone lines, one or more common batteries for supplying talking current to said telephone lines, a two-way trunk-line, automatic switches, means for transmitting switch operating electrical impulses over said trunk-line in one direction to establish connection with a called telephone line, means for transmitting switch operating electrical impulses over said 15 trunk-line in the opposite direction to establish connection with a called telephone line, a connector provided with relay-coils, and connections by which talking current is supplied through said connector relay-coils to the called subscriber's station. 20
- 25 32. In a telephone exchange system, the combination of an automatic telephone exchange, another automatic telephone exchange, telephone lines connecting with each 30 exchange, common batteries for supplying talking current to the telephone lines, a two-way trunk-line extending from one exchange to the other, automatic means at each exchange for trunking in opposite directions over said trunk-line, whereby a subscriber of either exchange may employ said trunk-line for calling a subscriber of the other exchange, a connector provided with relay-coils, and connections by which talking 35 current is supplied through said connector relay-coils to the called subscriber's station. 40
33. In a telephone exchange system, the combination of a repeater comprising means 45 for repeating voice currents, means for repeating switch operating impulses, and a talking circuit, said repeater being also provided with a pair of switching relays, one relay controlling the other, and each relay 50 controlling the talking circuit, a battery with connections for supplying talking current through the repeater to the talking circuit, a connector provided with relay-coils, and connections by which talking current is supplied through said connector relay-coils to the called subscriber's station. 55
34. In a telephone exchange system, the combination of a talking circuit, means for producing voice currents in said circuit, means for 60 producing switch operating impulses in said circuit, switches to be operated by said impulses, a repeater provided with a pair of relays controlling the talking circuit, one relay controlling the other, said repeater comprising means for repeating 65
- voice currents, means for repeating switch operating impulses, a battery with connections for supplying talking current through the repeater to the talking circuit, a connector provided with relay-coils, and connections by which talking current is supplied through said connector relay-coils to the called subscriber's station. 70
35. In a telephone exchange system, the combination of a talking circuit, means for inductively dividing said talking circuit, automatic switches, means for producing voice currents in said talking circuit, means for transmitting switch operating electrical impulses over said circuit, relays for repeating switch operating electrical impulses from one side of said inductive means to the other, a pair of relays controlling the circuit at one side of said inductive means, one relay controlling the other, a battery with connections for supplying talking current to the talking circuit, a connector provided with relay-coils, and connections by which talking current is supplied through said connector relay-coils to the called subscriber's station. 75
36. In a telephone exchange system, the combination of a pair of trunk-conductors, a pair of line relays provided with a grounded spring, a calling subscriber's telephone line, a battery for supplying talking current to said line, a pole-changing-relay controlling the supply of talking current to the said telephone line, controlling the ground circuit to the said ground spring, and provided with means for preventing establishment of a short-circuit between said trunk-conductors when the line relays are simultaneously energized, a connector provided with relay-coils, and connections by which talking current is supplied through said connector relay-coils to the called subscriber's station. 80
37. In a telephone exchange system, the combination of telephone lines, a trunk-line, automatic means for automatically trunking in one direction over said trunk-line, automatic means for automatically trunking in the opposite direction over said trunk-line, a centralized source of current supply for both operating said automatic means and supplying talking current to the said telephone lines, local trunk release circuits for effecting a release or disconnection when two subscribers are through talking, and means by which the release is initiated over the main circuit temporarily established between the two subscribers' lines. 85
38. In a telephone exchange system, the combination of telephone lines, a two-way trunk-line, a repeater and a selector for automatically trunking in one direction over said trunk-line, another repeater and a selector for automatically trunking in the opposite direction over said trunk-line, a battery for supplying current for 90
- 95
- 100
- 105
- 110

- 120
- 125
- 130

- operating said repeaters and selectors, subscribers' transmitters adapted to receive talking current over the said telephone lines from said battery, local trunk release circuits for effecting a release or disconnection when two subscribers are through talking, and means by which the release is initiated over the main circuit temporarily established between the two subscribers' lines.
- 5 39. In a telephone exchange system, the combination of a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection with the latter in the opposite direction, telephone lines each comprising but two parallel metallic conductors, common battery means for supplying both talking and switching current to the said telephone lines, local trunk release circuits for effecting a release or disconnection when two subscribers are through talking, and means by which the release is initiated over the main circuit temporarily established between the two subscribers' lines.
- 10 40. In a telephone exchange system, the combination of a two-way trunk-line, automatic means for automatically trunking over said trunk-line in one direction, automatic means for automatically trunking over said trunk-line in the opposite direction, the means for trunking in one direction being separate and distinct from the means for trunking in the other direction, but both means being allotted to and connected with the ends of said trunk-line, local trunk release circuits for effecting a release or disconnection when two subscribers are through talking, and means by which the release is initiated over the main circuit temporarily established between the two subscribers' lines.
- 15 41. In a telephone exchange system, the combination of a two-way trunk-line, a repeater and a selector allotted to and connected with one end of said trunk-line, another repeater and selector allotted to and connected with the other end of said trunk-line, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors, local trunk release circuits for effecting a release or disconnection when
- two subscribers are through talking, and means by which the release is initiated over the main circuit temporarily established between the two subscribers' lines.
- 20 42. In a telephone exchange system, the combination of telephone lines, one or more common batteries for supplying talking current to said telephone lines, a two-way trunk-line, automatic switches, means for transmitting switch operating electrical impulses over said trunk-line in one direction to establish connection with a called telephone line, means for transmitting switch operating electrical impulses over said trunk-line in the opposite direction to establish connection with a called telephone line, local trunk release circuits for effecting a release or disconnection when two subscribers are through talking, and means by which the release is initiated over the main circuit temporarily established between the two subscribers' lines.
- 25 43. In a telephone exchange system, the combination of an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, whereby a subscriber of either exchange may employ said trunk-line for calling a subscriber of the other exchange, local trunk release circuits for effecting a release or disconnection when two subscribers are through talking, and means by which the release is initiated over the main circuit temporarily established between the two subscribers' lines.
- 30 44. In a telephone exchange system, the combination of a repeater comprising means for repeating voice currents, means for repeating switch operating impulses, and a talking circuit, said repeater being also provided with a pair of switching relays, one relay controlling the other, and each relay controlling the talking circuit, a battery with connections for supplying talking current through the repeater to the talking circuit, local trunk release circuits for effecting a release or disconnection when two subscribers are through talking, and means by which the release is initiated over the main circuit temporarily established between the two subscribers' lines.
- 35 45. In a telephone exchange system, the combination of a talking circuit, means for producing voice currents in said circuit, means for producing switch operating impulses in said circuit, switches to be operated by said impulses, a repeater provided with a pair of relays controlling the talking circuit, one relay controlling the other, said repeater comprising

- means for repeating voice currents, means for repeating switch operating impulses, a battery with connections for supplying talking current through the repeater to the talking circuit, local trunk release circuits for effecting a release or disconnection when two subscribers are through talking, and means by which the release is initiated over the main circuit temporarily established between the two subscribers' lines. 5
46. In a telephone exchange system, the combination of a talking circuit, means for inductively dividing said talking circuit, automatic switches, means for producing voice currents in said talking circuit, means for transmitting switch operating electrical impulses over said circuit, relays for repeating switch operating electrical impulses from one side of said inductive means to the other, 10 a pair of relays controlling the circuit at one side of said inductive means, one relay controlling the other, a battery with connections for supplying talking current to the talking circuit, local trunk release circuits for effecting a release or disconnection when two subscribers are through talking, and means by which the release is initiated over the main circuit temporarily established between the two subscribers' lines. 15
47. In a telephone exchange system, the combination of a pair of trunk-conductors, a pair of line relays provided with a grounded spring, a calling subscriber's telephone line, a battery for supplying talking current to said line, a pole-changing-relay controlling the supply of talking current to the said telephone line, controlling the ground circuit to the said ground spring, and provided with means for preventing establishment of a short-circuit between said trunk-conductors when the line relays are simultaneously energized, local trunk release circuits for effecting a release or disconnection when two subscribers are through talking, 20 and means by which the release is initiated over the main circuit temporarily established between the two subscribers' lines. 25
48. In a telephone exchange system, the combination of telephone lines, a two-way trunk-line, a repeater and a selector for automatically trunking in one direction over said trunk-line, another repeater and a selector for automatically trunking in the opposite direction over said trunk-line, a 30 battery for supplying current for operating said repeaters and selectors, and subscribers' transmitters adapted to receive talking current over the said telephone lines from said battery, each repeater comprising a differential relay having differential windings which also serve as inductive resistance for feeding talking current to a calling subscriber's substation. 35
49. In a telephone exchange system, the combination of a two-way trunk-line com- 30
- posed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection with the latter in the opposite direction, telephone lines each comprising but two parallel metallic conductors, and common battery means for supplying both talking and switching current to the said telephone lines, 70 each repeater comprising a differential relay having differential windings which also serve as inductive resistance for feeding talking current to a calling subscriber's substation. 75
50. In a telephone exchange system, the combination of a two-way trunk-line, a repeater and a selector allotted to and connected with one end of said trunk-line, another repeater and selector allotted to and connected with the other end of said trunk-line, and means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors, each repeater comprising a differential relay having differential windings which also serve as inductive resistance for feeding talking current to a calling subscriber's substation. 80
51. In a telephone exchange system, the combination of a repeater comprising means for repeating voice currents, means for repeating switch operating impulses, and a talking circuit, said repeater being also provided with the switching relays *a* and *d*, 85 one relay controlling the other, and each relay controlling the talking circuit, and a battery with connections for supplying talking current through the repeater to the talking circuit, the said repeater comprising a differential relay having its differential windings temporarily connected for feeding talking current to a calling subscriber's substation. 90
52. In a telephone exchange system, the combination of a talking circuit, means for producing voice currents in said circuit, means for producing switch operating impulses in said circuit, switches to be operated by said impulses, a repeater provided with a 95 pair of relays controlling the talking circuit, one relay controlling the other, said repeater comprising means for repeating voice currents, means for repeating switch operating impulses, and a battery with connections for 100

- supplying talking current through the repeater to the talking circuit, the said repeater comprising a differential relay having its differential windings temporarily connected for feeding talking current to a calling subscriber's substation. 5
53. In a telephone exchange system, the combination of a talking circuit, means for inductively dividing said talking circuit, automatic switches, means for producing voice currents in said talking circuit, means for transmitting switch operating electrical impulses over said circuit, relays for repeating switch operating electrical impulses 10 from one side of said inductive means to the other, a pair of relays controlling the circuit at one side of said inductive means, one relay controlling the other, and a battery with connections for supplying talking current to the talking circuit, each repeater comprising a differential relay having differential windings which also serve as inductive resistance for feeding talking current to a calling subscriber's substation. 15
54. In a telephone system, the combination of a two-way trunk, selectors and repeaters for automatically trunking in opposite directions over said trunk, suitable means for supplying talking current to called subscribers' lines, and means for supplying talking current through the repeaters to calling subscribers' lines. 20
55. In a telephone system, the combination of a two-way trunk, suitable means for automatically trunking over said trunk in opposite directions, a talking circuit including said trunk, inductive connections in said trunk, a plurality of common batteries, and means for bridging said batteries across the talking circuit at opposite sides of said inductive connections to supply talking current to the subscribers' lines, said trunking means including means for repeating or relaying electrical impulses around said inductive connections. 25
56. In a telephone system, the combination of a two-way trunk, inductive connections in and for the opposite ends of said trunk, repeaters for repeating or relaying electrical impulses around said inductive connections, in opposite directions over said trunk, and means for supplying talking current from and over either end portion of said trunk to calling subscribers' lines. 30
57. In a telephone system, the combination of a two-way trunk, automatic means for trunking in opposite directions over said trunk, and means for supplying talking current from and over either end portion of said trunk to calling subscribers' lines. 35
58. In a telephone system, the combination of a trunk, means for supplying talking current to the subscriber's line from and over the opposite ends of said trunk, means for permitting voice-currents to pass over 40
- the middle portion of said trunk but excluding the same from the path of talking current to the subscribers' lines, and means for automatically trunking in opposite directions over said trunk. 45
59. In a telephone system, telephone lines, means for supplying talking current to calling telephone lines from either end of a two-way trunk, means for automatically selecting the trunk, and suitable means for extending connection from either end of said trunk, in combination with such trunk. 50
60. In a telephone system, trunk selectors for automatically selecting either end of an idle two-way trunk, suitable means for extending connection from either end of said trunk, and means for supplying talking current to calling subscribers' lines from either end of said trunk, in combination with such trunk. 55
61. In a telephone system, a two-way trunk provided at each end with an electrical impulse repeater for controlling switches, and with means distinct from said repeaters for extending connection from either end thereof. 60
62. In a telephone system, the combination of central means for supplying talking current, a two-way trunk, means for automatically selecting either end of said trunk from a predetermined group, and means for automatically trunking either way over said trunk, substantially as and for the purpose set forth. 65
63. In a telephone exchange system, telephone lines, a trunk-line, automatic means for automatically trunking in one direction over said trunk-line, automatic means for automatically trunking in the opposite direction over said trunk-line, having vertical motion to select groups and rotary motion to connect with a line in the selected group, and a centralized source of current-supply for both operating said automatic means and supplying talking current to the said telephone lines. 70
64. In a telephone exchange system, telephone lines, a two-way trunk-line, a repeater and a selector for automatically trunking in one direction over said trunk-line, said selector having vertical motion to select groups and rotary motion to connect with a line in the selected group, another repeater and a selector for automatically trunking in the opposite direction over said trunk-line, a battery for supplying current for operating said repeaters and selectors, and subscribers' transmitters adapted to receive talking current over the said telephone lines from said battery. 75
65. In a telephone exchange system, a two-way trunk-line composed of but two parallel metallic conductors, one-way trunk-lines each comprising three parallel metallic conductors, repeaters and selectors for connect- 80

ing a three-conductor trunk with the two-way trunk to automatically extend a trunking connection over the latter in one direction, repeaters and selectors for connecting a three-conductor trunk with the two-way trunk-line to automatically extend a trunking connection over the latter in the opposite direction, said selectors having vertical motion to select groups and rotary motion to

10 connect with a line in the selected group, telephone lines each comprising but two parallel metallic conductors, and common battery means for supplying both talking and switching current to the said telephone lines.

65. In a telephone exchange system, a two-way trunk-line, automatic means for automatically trunking over said trunk-line in one direction, having vertical motion to select groups and rotary motion to connect with a line in the selected group, and automatic means for automatically trunking over said trunk-line in the opposite direction, the means for trunking in one direction being

25 separate and distinct from the means for trunking in the other direction, but both means being allotted to and connected with the ends of said trunk-line.

67. In a telephone exchange system, a two-way trunk-line, a repeater and a selector allotted to and connected with one end of said trunk-line, another repeater and selector allotted to and connected with the other end of said trunk-line, said selector having vertical motion to select groups and rotary motion to connect with a line in the selected group, and means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors.

68. In a telephone exchange system, telephone lines, one or more common batteries for supplying talking current to said telephone lines, a two-way trunk-line, automatic switches having vertical motion to select groups and rotary motion to connect with a line in the selected group, means for transmitting switch-operating electrical impulses over said trunk-line in one direction to establish connection with a called telephone line, and means for transmitting switch-operating electrical impulses over said trunk-line in the opposite direction to establish connection with a called telephone line.

69. In a telephone exchange system, an automatic telephone exchange, another automatic telephone exchange, telephone lines connecting with each exchange, common batteries for supplying talking current to the telephone lines, a two-way trunk-line ex-

tending from one exchange to the other, and automatic means at each exchange for trunking in opposite directions over said trunk-line, having vertical motion to select groups and rotary motion to connect with a line in the selected group, whereby a subscriber of either exchange may employ said trunk-line for calling a subscriber of the other exchange.

70. In a telephone exchange system, a talking circuit, means for producing voice-currents in said circuit, means for producing switch-operating impulses in said circuit, switches to be operated by said impulses, having vertical motion to select groups and rotary motion to connect with a line in the selected group, a repeater provided with a pair of relays controlling the talking circuit, one relay controlling the other, said repeater comprising means for repeating voice-currents, means for repeating switch-operating impulses, and a battery with connections for supplying talking current through the repeater to the talking circuit.

71. In a telephone exchange system, a talking circuit, means for inductively dividing said talking circuit, automatic switches having vertical motion to select groups and rotary motion to connect with a line in the selected group, means for producing voice-currents in said talking circuit, means for transmitting switch-operating electrical impulses over said circuit, relays for repeating switch-operating electrical impulses from one side of said inductive means to the other, a pair of relays controlling the circuit at one side of said inductive means, one relay controlling the other, and a battery with connections for supplying talking current to the talking circuit.

72. In a telephone exchange system, trunks divided into groups, a selector having vertical motion to select groups and rotary motion to connect with a line in the selected group, provided with a vertical ratchet-pawl having a pin, ratchet-teeth, a double-dog provided with a pin, and a spring for causing said first-mentioned pin to engage said last-named pin.

73. In a telephone exchange system, trunks divided into groups, a selector having vertical motion to select groups and rotary motion to connect with a line in the selected group, provided with a vertical ratchet-pawl, ratchet-teeth, a double-dog, and means on the double-dog for engaging said vertical pawl.

74. In a telephone exchange system, the combination of telephone lines, a trunk-line, automatic means for automatically trunking in one direction over said trunk-line, automatic means for automatically trunking in the opposite direction over said trunk-line, having vertical motion to select groups and rotary motion to connect with a

line in the selected group, a centralized source of current-supply for both operating said automatic means and supplying talking current to the said telephone lines, a centralized source of ringing current, and means including a calling subscriber's switch for controlling the supply of ringing current to the called subscriber's station.

75. In a telephone exchange system, the combination of telephone lines, a two-way trunk-line, a repeater and a selector for automatically trunking in one direction over said trunk-line, said selector having vertical motion to select groups and rotary motion to connect with a line in the selected group, another repeater and a selector for automatically trunking in the opposite direction over said trunk-line, a battery for supplying current for operating said repeaters and selectors, subscribers' transmitters adapted to receive talking current over the said telephone lines from said battery, a centralized source of ringing current, and means including a calling subscriber's switch for controlling the supply of ringing current to the called subscriber's station.

76. In a telephone exchange system, the combination of a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection with the latter in the opposite direction, said selectors having vertical motion to select groups and rotary motion to connect with a line in the selected group, telephone lines each comprising but two parallel metallic conductors, common battery means for supplying both talking and switching current to the said telephone lines, a centralized source of ringing current, and means including a calling subscriber's switch for controlling the supply of ringing current to the called subscriber's station.

77. In a telephone exchange system, the combination of a two-way trunk-line, automatic means for automatically trunking over said trunk-line in one direction, having vertical motion to select groups and rotary motion to connect with a line in the selected group, automatic means for automatically trunking over said trunk-line in the opposite direction, the means for trunking in one direction being separate and distinct from the means for trunking in the other direction, but both means being allotted to and connected with the ends of said trunk-line, a centralized source of ringing current, and means including a calling subscriber's

switch for controlling the supply of ringing current to the called subscriber's station.

78. In a telephone exchange system, the combination of a two-way trunk-line, a repeater and a selector allotted to and connected with one end of said trunk-line, another repeater and selector allotted to and connected with the other end of said trunk-line, said selector having vertical motion to select groups and rotary motion to connect with a line in the selected group, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors, a centralized source of ringing current, and means including a calling subscriber's switch for controlling the supply of ringing current to the called subscriber's station.

79. In a telephone exchange system, the combination of telephone lines, one or more common batteries for supplying talking current to said telephone lines, a two-way trunk-line, automatic switches having vertical motion to select groups and rotary motion to connect with a line in the selected group, means for transmitting switch-operating electrical impulses over said trunk-line in one direction to establish connection with a called telephone line, means for transmitting switch-operating electrical impulses over said trunk-line in the opposite direction to establish connection with a called telephone line, a centralized source of ringing current, and means including a calling subscriber's switch for controlling the supply of ringing current to the called subscriber's station.

80. In a telephone exchange system, the combination of an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, having vertical motion to select groups and rotary motion to connect with a line in the selected group, whereby a subscriber of either exchange may employ said trunk-line for calling a subscriber of the other exchange, a centralized source of ringing current, and means including a calling subscriber's switch for controlling the supply of ringing current to the called subscriber's station.

81. In a telephone exchange system, the combination of a talking circuit, means for producing voice-currents in said circuit,

- means for producing switch-operating impulses in said circuit, switches to be operated by said impulses, having vertical motion to select groups and rotary motion to connect with a line in the selected group, a repeater provided with a pair of relays controlling the talking circuit, one relay controlling the other, said repeater comprising means for repeating voice-currents, means for repeating switch-operating impulses, a battery with connections for supplying talking current through the repeater to the talking circuit, a centralized source of ringing current, and means including a calling subscriber's switch for controlling the supply of ringing current to the called subscriber's station. 82. In a telephone exchange system, the combination of a talking circuit, means for inductively dividing said talking circuit, automatic switches having vertical motion to select groups and rotary motion to connect with a line in the selected group, means for producing voice-currents in said talking circuit, means for transmitting switch-operating electrical impulses over said circuit, relays for repeating switch-operating electrical impulses from one side of said inductive means to the other, a pair of relays controlling the circuit at one side of said inductive means, one relay controlling the other, a battery with connections for supplying talking current to the talking circuit, a centralized source of ringing current, and means including a calling subscriber's switch for controlling the supply of ringing current to the called subscriber's station. 83. In a telephone exchange system, the combination of telephone lines, a trunk-line, automatic means for automatically trunking in one direction over said trunk-line, automatic means for automatically trunking in the opposite direction over said trunk-line, having vertical motion to select groups and rotary motion to connect with a line in the selected group, a centralized source of current-supply for both operating said automatic means and supplying talking current to the said telephone lines, a connector provided with relay-coils, and connections by which talking current is supplied through said connector relay-coils to the called subscriber's station. 84. In a telephone exchange system, the combination of telephone lines, a two-way trunk-line, a repeater and a selector for automatically trunking in one direction over said trunk-line, said selector having vertical motion to select groups and rotary motion to connect with a line in the selected group, another repeater and a selector for automatically trunking in the opposite direction over said trunk-line, a battery for applying current for operating said repeaters and selectors, subscribers' transmitters adapted to receive talking current over the said telephone lines from said battery, a connector provided with relay-coils, and connections by which talking current is supplied through said connector relay-coils to the called subscriber's station. 85. In a telephone exchange system, the combination of a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection with the latter in the opposite direction, said selectors having vertical motion to select groups and rotary motion to connect with a line in the selected group, telephone lines each comprising but two parallel metallic conductors, common battery means for supplying both talking and switching current to the said telephone lines, a connector provided with relay-coils, and connections by which talking current is supplied through said connector relay-coils to the called subscriber's station. 86. In a telephone exchange system, the combination of a two-way trunk-line, automatic means for automatically trunking over said trunk-line in one direction, having vertical motion to select groups and rotary motion to connect with a line in the selected group, automatic means for automatically trunking over said trunk-line in the opposite direction, the means for trunking in one direction being separate and distinct from the means for trunking in the other direction, but both means being allotted to and connected with the ends of said trunk-line, a connector provided with relay-coils, and connections by which talking current is supplied through said connector relay-coils to the called subscriber's station. 87. In a telephone exchange system, the combination of a two-way trunk-line, a repeater and a selector allotted to and connected with one end of said trunk-line, another repeater and selector allotted to and connected with the other end of said trunk-line, said selector having vertical motion to select groups and rotary motion to connect with a line in the selected group, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selector. 100 105 110 115 120 125 130

tors, a connector provided with relay-coils, and connections by which talking current is supplied through said connector relay-coils to the called subscriber's station.

88. In a telephone exchange system, the combination of telephone lines, one or more common batteries for supplying talking current to said telephone lines, a two-way trunk-line, automatic switches having vertical motion to select groups and rotary motion to connect with a line in the selected group, means for transmitting switch-operating electrical impulses over said trunk-line in one direction to establish connection with a called telephone line, means for transmitting switch-operating electrical impulses over said trunk-line in the opposite direction to establish connection with a called telephone line, a connector provided with relay-coils, and connections by which talking current is supplied through said connector relay-coils to the called subscriber's station.

89. In a telephone exchange system, the combination of an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, having vertical motion to select groups and rotary motion to connect with a line in the selected group, whereby a subscriber of either exchange may employ said trunk-line for calling a subscriber of the other exchange, a connector provided with relay-coils, and connections by which talking current is supplied through said connector relay-coils to the called subscriber's station.

90. In a telephone exchange system, the combination of a talking circuit, means for producing voice-currents in said circuit, means for producing switch-operating impulses in said circuit, switches to be operated by said impulses having vertical motion to select groups and rotary motion to connect with a line in the selected group, a repeater provided with a pair of relays controlling the talking circuit, one relay controlling the other, said repeater comprising means for repeating voice-currents, means for repeating switch-operating impulses, a battery with connections for supplying talking current through the repeater to the talking circuit, a connector provided with relay-coils, and connections by which talking current is supplied through said connector relay-coils to the called subscriber's station.

91. In a telephone exchange system, the combination of a talking circuit, means for inductively dividing said talking circuit, automatic switches having vertical motion

to select groups and rotary motion to connect with a line in the selected group, means for producing voice-currents in said talking circuit, means for transmitting switch-operating electrical impulses over said circuit, 70 relays for repeating switch-operating electrical impulses from one side of said inductive means to the other, a pair of relays controlling the circuit at one side of said inductive means, one relay controlling the other, 75 a battery with connections for supplying talking current to the talking circuit, a connector provided with relay-coils, and connections by which talking current is supplied through said connector relay-coils to 80 the called subscriber's station.

92. In a telephone exchange system, the combination of telephone lines, a trunk-line, automatic means for automatically trunking in one direction over said trunk-line, automatic means for automatically trunking in the opposite direction over said trunk-line, having vertical motion to select groups and rotary motion to connect with a line in the selected group, a centralized source of current supply for both operating said automatic means and supplying talking current to the said telephone lines, local trunk-release circuits for effecting a release or disconnection when two subscribers are through 90 talking, and means by which the release is initiated over the main circuit temporarily established between the two subscribers' lines.

93. In a telephone exchange system, the combination of telephone lines, a two-way 100 trunk-line, a repeater and a selector for automatically trunking in one direction over said trunk-line, said selector having vertical motion to select groups and rotary motion to connect with a line in the selected group, another repeater and a selector for automatically trunking in the opposite direction over said trunk-line, a battery for supplying current for operating said repeaters and selectors, subscribers' transmitters adapted to receive talking current over the said telephone lines from said battery, local trunk-release circuits for effecting a release or disconnection when two subscribers are through talking, and means by which the release is initiated over the main circuit temporarily established between the two subscribers' lines. 110 115

94. In a telephone exchange system, the combination of a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over 120 the latter in one direction, repeaters and selectors for connecting a three-conductor trunk with the two-way trunk-line to automatically extend a trunking connection with the latter in the opposite direction, said se- 125 130

- lectors having vertical motion to select groups and rotary motion to connect with a line in the selected group, telephone lines each comprising but two parallel metallic conductors, common battery means for supplying both talking and switching current to the said telephone lines, local trunk-release circuits for effecting a release or disconnection when two subscribers are through talking, and means by which the release is initiated over the main circuit temporarily established between the two subscribers' lines.
95. In a telephone exchange system, the combination of an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, having vertical motion to select groups and rotary motion to connect with a line in the selected group, whereby a subscriber of either exchange may employ said trunk-line for calling a subscriber of the other exchange, local trunk-release circuits for effecting a release or disconnection when two subscribers are through talking, and means by which the release is initiated over the main circuit temporarily established between the two subscribers' lines.
96. In a telephone exchange system, the combination of a two-way trunk-line, a repeater and a selector allotted to and connected with one end of said trunk-line, another repeater and selector allotted to and connected with the other end of said trunk-line, said selector having vertical motion to select groups and rotary motion to connect with a line in the selected group, means for controlling said repeaters and selectors, the selector at one end of the trunk-line being adapted to cooperate with the repeater at the other end for trunking in one direction, and the other repeater and selector being adapted for trunking in the opposite direction, said repeaters being units in themselves and separate and distinct from said selectors, local trunk-release circuits for effecting a release or disconnection when two subscribers are through talking, and means by which the release is initiated over the main circuit temporarily established between the two subscribers' lines.
97. In a telephone exchange system, the combination of telephone lines, one or more common batteries for supplying talking current to said telephone lines, a two-way trunk-line, automatic switches having vertical motion to select groups and rotary motion to connect with a line in the selected group, means for transmitting switch-operating electrical impulses over said trunk-line in one direction to establish connection with a called telephone line, means for transmitting switch-operating electrical impulses over said trunk-line in the opposite direction to establish connection with a called telephone line, local trunk-release circuits for effecting a release or disconnection when two subscribers are through talking, and means by which the release is initiated over the main circuit temporarily established between the two subscribers' lines.
98. In a telephone exchange system, the combination of an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, having vertical motion to select groups and rotary motion to connect with a line in the selected group, whereby a subscriber of either exchange may employ said trunk-line for calling a subscriber of the other exchange, local trunk-release circuits for effecting a release or disconnection when two subscribers are through talking, and means by which the release is initiated over the main circuit temporarily established between the two subscribers' lines.
99. In a telephone exchange system, the combination of a talking circuit, means for producing voice-currents in said circuit, means for producing switch-operating impulses in said circuit, switches to be operated by said impulses, having vertical motion to select groups and rotary motion to connect with a line in the selected group, a repeater provided with a pair of relays controlling the talking circuits, one relay controlling the other, said repeater comprising means for repeating voice-currents, means for repeating switch-operating impulses, a battery with connections for supplying talking current through the repeater to the talking circuit, local trunk-release circuits for effecting a release or disconnection when two subscribers are through talking, and means by which the release is initiated over the main circuit temporarily established between the two subscribers' lines.
100. In a telephone exchange system, the combination of a talking circuit, means for inductively dividing said talking circuit, automatic switches having vertical motion to select groups and rotary motion to connect with a line in the selected group, means for producing voice-currents in said talking circuit, means for transmitting switch-operating electrical impulses over said circuit, relays for repeating switch-operating electrical impulses from one side of said inductive means to the other, a pair of relays controlling the circuit at one side of said inductive means, one relay controlling the

other, a battery with connections for supplying talking current to the talking circuit, local trunk-release circuits for effecting a release or disconnection when two subscribers are through talking, and means by which the release is initiated over the main circuit temporarily established between the two subscribers' lines.

101. In a telephone exchange system, the combination of telephone lines, a two-way trunk-line, a repeater and a selector for automatically trunking in one direction over said trunk-line, said selector having vertical motion to select groups and rotary motion to connect with a line in the selected group, another repeater and a selector for automatically trunking in the opposite direction over said trunk-line, a battery for supplying current for operating said repeaters and selectors, and subscribers' transmitters adapted to receive talking current over the said telephone lines from said battery, each repeater comprising a differential relay having differential windings which also serve as inductive resistance for feeding talking current to a calling subscriber's substation.

102. In a telephone exchange system, the combination of a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection with the latter in the opposite direction, said selectors having vertical motion to select groups and rotary motion to connect with a line in the selected group, telephone lines each comprising but two parallel metallic conductors, and common battery means for supplying both talking and switching current to the said telephone lines, each repeater comprising a differential relay having differential windings which also serve as inductive resistance for feeding talking current to a calling subscriber's substation.

103. In a telephone exchange system, the combination of a two-way trunk-line, a repeater and a selector allotted to and connected with one end of said trunk-line, another repeater and selector allotted to and connected with the other end of said trunk-line, said selector having vertical motion to select groups and rotary motion to connect with a line in the selected group, and means for controlling said repeaters and selectors, the selector at one end of the trunk-line being adapted to coöperate with the repeater at the other end for trunking in one direction, and the other repeater and selector being adapted for trunking in the opposite

direction, said repeaters being units in themselves and separate and distinct from said selectors, each repeater comprising a differential relay having differential windings which also serve as inductive resistance for feeding talking current to a calling subscriber's substation.

104. In a telephone exchange system, the combination of a talking circuit, means for producing voice-currents in said circuit, means for producing switch-operating impulses in said circuit, switches to be operated by said impulses, having vertical motion to select groups and rotary motion to connect with a line in the selected group, a repeater provided with a pair of relays controlling the talking circuit, one relay controlling the other, said repeater comprising means for repeating voice-currents, means for repeating switch-operating impulses, and a battery with connections for supplying talking current through the repeater to the talking circuit, the said repeater comprising a differential relay having its differential windings temporarily connected for feeding talking current to a calling subscriber's substation.

105. In a telephone exchange system, the combination of a talking circuit, means for inductively dividing said talking circuit, automatic switches having vertical motion to select groups and rotary motion to connect with a line in the selected group, means for producing voice-currents in said talking circuit, means for transmitting switch-operating electrical impulses over said circuit, relays for repeating switch-operating electrical impulses from one side of said inductive means to the other, a pair of relays controlling the circuit at one side of said inductive means, one relay controlling the other, and a battery with connections for supplying talking current to the talking circuit, each repeater comprising a differential relay having differential windings which also serve as inductive resistance for feeding talking current to a calling subscriber's substation.

106. In a telephone system, the combination of a two-way trunk, selectors and repeaters for automatically trunking in opposite directions over said trunk, said selectors having vertical motion to select groups and rotary motion to connect with a line in the selected group, suitable means for supplying talking current to called subscribers' lines, and means for supplying talking current through the repeaters to calling subscribers' lines.

107. In a telephone system, the combination of a two-way trunk, suitable means for automatically trunking over said trunk in opposite directions, having vertical motion to select groups and rotary motion to connect with a line in the selected group, a talking circuit including said trunk, induct-

- 5 tive connections in said trunk, a plurality of common batteries, and means for bridging said batteries across the talking circuit at opposite sides of said inductive connections to supply talking current to the subscribers' lines, said trunking means including means for repeating or relaying electrical impulses around said inductive connections.
108. In a telephone system, the combination of a two-way trunk, inductive connections in and for the opposite ends of said trunk, repeaters for repeating or relaying electrical impulses around said inductive connections in opposite directions over said 10 trunk, switches having vertical motion to select groups and rotary motion to connect with a line in the selected group, and means for supplying talking current from and over either end portion of said trunk 20 to calling subscribers' lines.
109. In a telephone system, the combination of a two-way trunk, automatic means for trunking in opposite directions over said trunk, having vertical motion to select 25 groups and rotary motion to connect with a line in the selected group, and means for supplying talking current from and over either end portion of said trunk to calling subscribers' lines.
110. In a telephone system, the combination of a trunk, means for supplying talking current to the subscriber's line from and over the opposite ends of said trunk, means for permitting voice-currents to pass over 30 the middle portion of said trunk but excluding the same from the path of talking current to the subscribers' lines, and means for automatically trunking in opposite directions over said trunk, having vertical motion to select groups and rotary motion to connect with a line in the selected group.
111. In a telephone system, telephone lines, means for supplying talking current to calling telephone lines from either end 45 of a two-way trunk, means for automatically selecting the trunk, and suitable means for extending connection from either end of said trunk, having vertical motion to select groups and rotary motion to connect 50 with a line in the selected group, in combination with such trunk.
112. In a telephone system, trunk selectors for automatically selecting either end of an idle two-way trunk, suitable means for 55 extending connection from either end of said trunk, having vertical motion to select groups and rotary motion to connect with a line in the selected group, and means for supplying talking current to calling subscribers' lines from either end of said trunk, in combination with such trunk.
113. In a telephone system, a two-way trunk provided at each end with an electrical impulse repeater for controlling 60 switches, and with means distinct from said repeaters for extending connection from either end thereof, having vertical motion to select groups and rotary motion to connect with a line in the selected group.
114. In a telephone system, the combination of automatic switches having vertical and rotary motion for trunking in opposite directions over one and the same trunk, so that the trunk may be used for calling in either direction, and common battery means for supplying talking current to one or more of the subscribers' lines.
115. In a system in which the subscribers' lines are in groups, telephone lines, a trunk-line, automatic means for automatically trunking in one direction over said trunk-line, automatic means for automatically trunking in the opposite direction over said trunk-line, a centralized source of current supply for both operating said automatic means and supplying talking current to the said telephone lines, and means having vertical motion to select groups and then rotary motion under substation control to connect with the called line in any selected group.
116. In a system in which the subscribers' lines are in groups, telephone lines, a two-way trunk-line, a repeater and a selector for automatically trunking in one direction over said trunk-line, another repeater and a selector for automatically trunking in the opposite direction over said trunk-line, a battery for supplying current for operating said repeaters and selectors, subscribers' transmitters adapted to receive talking current over the said telephone lines from said battery, and means having vertical motion to select groups and then rotary motion under substation control to connect with the called line in any selected group.
117. In a system in which the subscribers' lines are in groups, a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection over the latter in the opposite direction, telephone lines each comprising but two parallel metallic conductors, common battery means for supplying both talking and switching current to the said telephone lines, and means having vertical motion to select groups and then rotary motion under substation control to connect with the called line in any selected group.
118. In a system in which the subscribers' lines are in groups, a two-way trunk-line, automatic means for automatically trunk-

ing over said trunk-line in one direction, automatic means for automatically trunking over said trunk-line in the opposite direction, the means for trunking in one direction being separate and distinct from the means for trunking in the other direction, but both means being allotted to and connected with the ends of said trunk-line, and means having vertical motion to select groups and then rotary motion under substation control to connect with the called line in any selected group.

119. In a system in which the subscribers' lines are in groups, a two-way trunk-line, a repeater and a selector allotted to and connected with one end of said trunk-line, another repeater and selector allotted to and connected with the other end of said trunk-line, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors, and means having vertical motion to select groups and then rotary motion under substation control to connect with the called line in any selected group.

120. In a system in which the subscribers' lines are in groups, telephone lines, one or more common batteries for supplying talking current to said telephone lines, a two-way trunk-line, automatic switches, means for transmitting switch operating electrical impulses over said trunk-line in one direction to establish connection with a called telephone line, means for transmitting switch operating electrical impulses over said trunk-line in the opposite direction to establish connection with a called telephone line, and means having vertical motion to select groups and then rotary motion under substation control to connect with the called line in any selected group.

121. In a system in which the subscribers' lines are in groups, an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, whereby a subscriber of either exchange may employ said trunk-line for calling a subscriber of the other exchange, and means having vertical motion to select groups and then rotary motion under substation control to connect with the called line in any selected group.

122. In a system in which the subscribers'

lines are in groups, a repeater comprising means for repeating voice currents, means for repeating switch operating impulses, a talking circuit, said repeater being also provided with a pair of switching relays, one relay controlling the other, each relay controlling the talking circuit, a battery with connections for supplying talking current through the repeater to the talking circuit, and means having vertical motion to select groups and then rotary motion under substation control to connect with the called line in any selected group.

123. In a system in which the subscribers' lines are in groups, a talking circuit, means for producing voice currents in said circuit, means for producing switch operating impulses in the conductors of said circuit, switches to be operated by said impulses, a repeater provided with a pair of relays controlling the talking circuit, one relay controlling the other, said repeater comprising means for repeating voice currents, means for repeating switch operating impulses, a battery with connections for supplying talking current through the repeater to the talking circuit, and means having vertical motion to select groups and then rotary motion under substation control to connect with the called line in any selected group.

124. In a system in which the subscribers' lines are in groups, a talking circuit, means for inductively dividing said talking circuit, automatic switches, means for producing voice currents in said talking circuit, means for transmitting switch operating electrical impulses over the conductors of said circuit, relays for repeating switch operating electrical impulses from one side of said inductive means to the other, a pair of relays controlling the circuit at one side of said inductive means, one relay controlling the other, a battery with connections for supplying talking current to the talking circuit, and means having vertical motion to select groups and then rotary motion under substation control to connect with the called line in any selected group.

125. In a system in which the subscribers' lines are in groups, selectors and connectors for extending connection from one subscriber to another, a pair of trunk-conductors, a pair of line relays provided with a grounded spring, a calling subscriber's telephone line, a battery for supplying talking current to said line, a pole-changing relay controlling the supply of talking current to the said telephone line, controlling the ground circuit to the said ground spring, and provided with means for preventing establishment of a short-circuit between said trunk-conductors when the line relays are simultaneously energized, said connectors having vertical motion to select groups and then rotary motion under substation control

to connect with the called line in any selected group.

126. In a system for establishing talking circuits between calling and called subscribers' lines, telephone lines, a trunk-line, automatic means for automatically trunking in one direction over said trunk-line, automatic means for automatically trunking in the opposite direction over said trunk-line, a centralized source of current supply for both operating said automatic means and supplying talking current to the said telephone lines, bridges containing operating elements adapted to be placed across the conductors of any talking circuit during the establishment of a connection, and means for reducing the number of said bridges.

127. In a system for establishing talking circuits between calling and called subscribers' lines, telephone lines, a two-way trunk-line, a repeater and a selector for automatically trunking in one direction over said trunk-line, another repeater and a selector for automatically trunking in the opposite direction over said trunk-line, a battery for supplying current for operating said repeaters and selectors, subscribers' transmitters adapted to receive talking current over the said telephone lines, and said battery, bridges containing operating elements adapted to be placed across the conductors of any talking circuit during the establishment of a connection, and means for reducing the number of said bridges.

128. In a system for establishing talking circuits between calling and called subscribers' lines, a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection over the latter in the opposite direction, telephone lines each comprising but two parallel metallic conductors, common battery means for supplying both talking and switching current to the said telephone lines, bridges containing operating elements adapted to be placed across the conductors of any talking circuit during the establishment of a connection, means for reducing the number of said bridges.

129. In a system for establishing talking circuits between calling and called subscribers' lines, a two-way trunk-line, automatic means for automatically trunking over said trunk-line in one direction, automatic means for automatically trunking over said trunk-line in the opposite direction, the means for trunking in one direction being separate

and distinct from the means for trunking in the other direction, but both means being allotted to and connected with the ends of said trunk-line, bridges containing operating elements adapted to be placed across the conductors of any talking circuit during the establishment of a connection, and means for reducing the number of said bridges.

130. In a system for establishing talking circuits between calling and called subscribers' lines, a two-way trunk-line, a repeater and a selector allotted to and connected with one end of said trunk-line, another repeater and selector allotted to and connected with the other end of said trunk-line, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selectors, bridges containing operating elements adapted to be placed across the conductors of any talking circuit during the establishment of a connection, and means for reducing the number of said bridges.

131. In a system for establishing talking circuits between calling and called subscribers' lines, telephone lines, one or more common batteries for supplying talking current to said telephone lines, a two-way trunk-line, automatic switches, means for transmitting switch operating electrical impulses over said trunk-line in one direction to establish connection with a called telephone line, means for transmitting switch operating electrical impulses over said trunk line in the opposite direction to establish connection with a called telephone line, bridges containing operating elements adapted to be placed across the conductors of any talking circuit during the establishment of a connection, and means for reducing the number of said bridges.

132. In a system for establishing talking circuits between calling and called subscribers' lines, an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, whereby a subscriber of either exchange may employ said trunk-line for calling a subscriber of the other exchange, bridges containing operating elements adapted to be placed across the conductors of any talking circuit during the establishment of a connection, and means for reducing the number of said bridges.

133. In a system for establishing talking

circuits between calling and called subscribers' lines, a repeater comprising means for repeating voice currents, means for repeating switch operating impulses, a talking circuit, said repeater being also provided with a pair of switching relays, one relay controlling the other, each relay controlling the talking circuit, a battery with connections for supplying talking current through the repeater to the talking circuit, bridges containing operating elements adapted to be placed across the conductors of any talking circuit during the establishment of a connection, and means for reducing the number of said bridges.

134. In a system for establishing talking circuits between calling and called subscribers' lines, a talking circuit, means for producing voice currents in said circuit, means for producing switch operating impulses in the conductors of said circuit, switches to be operated by said impulses, a repeater provided with a pair of relays controlling the talking circuit, one relay controlling the other, said repeater comprising means for repeating voice currents, means for repeating switch operating impulses, a battery with connections for supplying talking current through the repeater to the talking circuit, bridges containing operating elements adapted to be placed across the conductors of any talking circuit during the establishment of a connection, and means for reducing the number of said bridges.

135. In a system for establishing talking circuits between calling and called subscribers' lines, a talking circuit, means for inductively dividing said talking circuit, automatic switches, means for producing voice currents in said talking circuit, means for transmitting switch operating electrical impulses over the conductors of said circuit, relays for repeating switch operating electrical impulses from one side of said inductive means to the other, a pair of relays controlling the circuit at one side of said inductive means, one relay controlling the other, a battery with connections for supplying talking current to the talking circuit, bridges containing operating elements adapted to be placed across the conductors of any talking circuit during the establishment of a connection, and means for reducing the number of said bridges.

136. In a system in which the trunks are in groups, means for preselecting a particular group, telephone lines, a trunk-line, automatic means for automatically trunking in one direction over said trunk-line, automatic means for automatically trunking in the opposite direction over said trunk-line, a centralized source of current supply for both operating said automatic means and supplying talking current to the said tele-

phone lines, and means for automatically selecting an idle trunk in a preselected group.

137. In a system in which the trunks are in groups, means for preselecting a particular group, telephone lines, a two-way trunk-line, a repeater and a selector for automatically trunking in one direction over said trunk-line, another repeater and a selector for automatically trunking in the opposite direction over said trunk-line, a battery for supplying current for operating said repeaters and selectors, subscribers' transmitters adapted to receive talking current over the said telephone lines from said battery, and means for automatically selecting an idle trunk in a preselected group.

138. In a system in which the trunks are in groups, means for preselecting a particular group, a two-way trunk-line composed of but two parallel metallic conductors, one-way trunk-lines each comprising three parallel metallic conductors, repeaters and selectors for connecting a three-conductor trunk with the two-way trunk to automatically extend a trunking connection over the latter in one direction, repeaters and selectors for connecting a three-conductor trunk with the two-way trunk-line to automatically extend a trunking connection over the latter in the opposite direction, telephone lines each comprising but two parallel metallic conductors, common battery means for supplying both talking and switching current to the said telephone lines, and means for automatically selecting an idle trunk in a preselected group.

139. In a system in which the trunks are in groups, means for preselecting a particular group, a two-way trunk-line, automatic means for automatically trunking over said trunk-line in one direction, automatic means for automatically trunking over said trunk-line in the opposite direction, the means for trunking in one direction being separate and distinct from the means for trunking in the other direction, but both means being allotted to and connected with the ends of said trunk-line, and means for automatically selecting an idle trunk in a preselected group.

140. In a system in which the trunks are in groups, means for preselecting a particular group, a two-way trunk-line, a repeater and a selector allotted to and connected with one end of said trunk-line, another repeater and selector allotted to and connected with the other end of said trunk-line, means for controlling said repeaters and selectors, the selector at one end of the trunk-line being adapted to coöperate with the repeater at the other end for trunking in one direction, and the other repeater and selector being adapted for trunking in the opposite direction, said repeaters being units in themselves and separate and distinct from said selec-

tors, and means for automatically selecting an idle trunk in a preselected group.

141. In a system in which the trunks are in groups, means for preselecting a particular group, telephone lines, one or more common batteries for supplying talking current to said telephone lines, a two-way trunk-line, automatic switches, means for transmitting switch operating electrical impulses over said trunk-line in one direction to establish connection with a called telephone line, means for transmitting switch operating electrical impulses over said trunk-line in the opposite direction to establish connection with a called telephone line, and means for automatically selecting an idle trunk in a preselected group.

142. In a system in which the trunks are in groups, means for preselecting a particular group, an automatic telephone exchange, another automatic telephone exchange, telephone lines connecting with each exchange, common batteries for supplying talking current to the telephone lines, a two-way trunk-line extending from one exchange to the other, automatic means at each exchange for trunking in opposite directions over said trunk-line, whereby a subscriber of either exchange may employ said trunk-line for calling a subscriber of the other exchange, and means for automatically selecting an idle trunk in a preselected group.

143. In a system in which the trunks are in groups, means for preselecting a particular group, a pair of trunk-conductors,

a pair of line relays provided with a grounded spring, a calling subscriber's telephone line, a battery for supplying talking current to said line, a pole-changing relay 40 controlling the supply of talking current to the said telephone line, controlling the ground circuit to the said ground spring, and provided with means for preventing establishment of a short-circuit between 45 said trunk-conductors when the line relays are simultaneously energized, and means for automatically selecting an idle trunk in a preselected group.

144. In a telephone system in which the trunks are in groups, a trunk, a repeater mechanism for each end of said trunk, and a selector for each end of said trunk, each selector being controllable by the repeater mechanism at the other end of the trunk 55 and having first one motion to select groups and then another motion to automatically select an idle trunk in the predetermined group.

145. In a telephone system having 60 selectors and repeaters, an automatic repeating trunk having selector relays and repeater relays which are exactly the same at each end thereof, said selectors having 65 vertical and rotary movement.

Signed by me at Chicago, Cook county, Illinois, this 11th day of June, 1906.

TALBOT G. MARTIN.
